UNITED STATES PATENT OFFICE.

FRITZ ALDENDORFF, OF WILMERSDORF, BERLIN, GERMANY.

MACHINE-SWITCHING TELEPHONE SYSTEM.

Application filed December 17, 1914. Serial No. 877,781.

(GRANTED UNDER THE PROVISIONS OF THE ACT OF MARCH 3, 1921, 41 STAT. L., 1313.)

To all whom it may concern:

Be it known that I, FRITZ ALDENDORFF, 32 Mannheimerstrasse, Wilmersdorf, Berlin, Germany, engineer, have invented certain new and useful Improvements in Machine-Switching Telephone Systems, of which the following is a clear specification.

This invention relates in general to electro-mechanically controlled telephone systems and more particularly to systems of this kind in which the numerical switches set by the selecting or dialing impulses of the calling parties are placed in "branch paths" or "by-paths" as distinguished from the "main paths" or conversational circuits or trunks through which the talking currents are conducted from one talking party to another. By-path systems of various kinds are known, one kind of such system being shown in my United States Patent No. 1321795. This invention relates amongst other features to certain features which, while partly shown in said patent, are not claimed therein. The numerical switches i. e. the switches set by dialing impulses, of the system claimed herein, after being sent onto a certain bank contact or set of bank contacts, do not execute any subsequent hunting operation for the purpose of finding an idle trunk, this operation being performed by purely non-numerical switches, said as switches or mechanisms that are not set by the subscribers' dialing impulses, but only by automatic arrangements that operate independently of the dialing or numerical impulses determined by the calling party.

The new features and combinations will appear in the following description, drawings and claims.

The invention is illustrated in the drawing in which Fig. 1 shews the general outlay of a system in which the establishing of each connection involves one group-selecting act.

Figs. 2 and 3 shew the outlay of a system in which two group selecting acts are involved in each connection and Figs. 4 and 5 shew a system requiring three group-selecting acts in the establishing of a talking connection.

Figs. 6 to 12 illustrate the details of the

switches of a system according to Fig. 1. Fig. 7 should be placed at the right side of Fig. 6, Fig. 7^a above Fig. 7, Fig. 8 beside Fig. 7, Fig. 9 beside Fig. 8, Fig. 10 beside Fig. 9, Fig. 11 beneath Fig. 8 and Fig. 12 beneath Fig. 9.

Fig. 13 illustrates the identifying means of the secondary trunk finders.

Fig. 14 shews a system in which secondary trunk finders are omitted.

Figs. 15 and 16 indicate how the trunking efficiency of a system without secondary finders may be improved.

Figs. 17 and 18 illustrate methods of reducing the number of finders employed in systems according to Figs. 1 to 13.

Fig. 18^a shows diagrammatically the trunk hunting switches which extend connections from the trunks of Fig. 18.

Fig. 19 shews an application of the invention to a system without group selectors and

Figs. 20^a and 20^b illustrate how forwardly-acting primary trunk finders may be used instead of revertively-acting primary trunk finders.

A general idea of the new system may be imparted with the aid of Fig. 1. In this figure three groups of subscribers or switches are indicated. The subscribers' stations 1¹, 2¹, 3¹ of the first group are connected to quick-acting finders 7¹, 8¹ to "calling line connectors" 4¹, 5¹, 6¹ to "wanted line selectors" 26¹, 27¹ and to the fixed contacts of "wanted line connectors" 28¹, 29¹, 30¹. The subscribers' stations 1¹¹, 2¹¹, 3¹¹ of the second group and the stations 1¹¹¹, 2¹¹¹, 3¹¹¹ of the third group are connected like the first group to four different groups of switches. In addition to these switches each subscribers' group may have a set of calling line-connector-finders 11, 12 (whose office it is to connect an idle quick-acting finder to an idle calling line connector) a set of group selectors 13, 14, a set of group selector connectors 9, 10, a set of primary trunk finders 18, 19, 20 a set of secondary trunk finders 15, 16, 17 and a set of wanted-line-selector-connectors 24, 25. Similar switches in the different subscribers' groups are denoted by similar reference numerals which

90

95

100

have exponents that correspond to their particular groups.

The general method of connecting a calling line to a wanted line will now be explained—Suppose a subscriber 2¹ of the first group establishes a connection with a subscriber 3¹¹¹ of the third group. The switches of the system operate as follows: When the calling subscriber 2¹ removes his receiver from the hook a quick-acting finder, for example 7¹, moves its movable contacts into connection with the calling line 102 and causes a connection to be established between the calling subscriber and an idle group selector, e. g., 13¹, through a calling line connector finder, e. g., 11¹ and a group selector connector 9¹. The calling line connector finders 11¹, 12¹ are arranged so that they are caused to hunt for a new idle calling line connector as soon as their quick-acting finders 7¹, 8¹ have completed their function of setting a calling line connector onto a calling line and the group selector connectors 9¹, 10¹ are arranged so that when their functions in connection with a certain call are completed they start hunting for a calling line connector 4¹, 5¹ or 6¹ to which a calling line connector finder has already connected itself. The calling line connectors 30 are arranged so that they start moving as soon as a quick-acting finder that happens to be connected to them makes connection with a calling line. Thus a calling line connector 5¹ to which a finder 7¹ is connected 35 will start moving as soon as the finder 7¹ reaches a calling line and will then also put its brushes into connection with the calling line. Should the calling subscriber 2¹ start sending in his selecting impulses before the connector 5¹ has reached his line the selecting impulses will flow through 7¹, 11¹, 9¹ to the group selector 13¹. But as soon as the connector 5¹ reaches the line 102 the path through 11¹ and 7¹ is interrupted by 40 the finder 11¹ connecting its quick-acting finder 7¹ to some other idle calling line connector, e. g. 6¹. The selecting impulses from the calling subscriber then flow through 5¹, 9¹ to the group selector 13¹. Since the calling subscriber 2¹ desires to connect to a subscriber 3¹¹¹ of the third group, he sends in 45 a number of group selecting impulses that causes the group selector 13¹ to select the selecting wire 36 that leads to the motor magnets 21¹¹¹, 22¹¹¹, 23¹¹¹ of the primary trunk finders 18¹¹¹, 19¹¹¹, 20¹¹¹ of the desired 50 third group.

It will be seen from Fig. 1 that for each group of secondary trunk finders 15¹, 16¹, 17¹—15¹¹¹, 16¹¹¹, 17¹¹¹—15¹¹¹, 16¹¹¹, 17¹¹¹ there is a set of trunks 37¹, 38¹, 39¹ and 37¹¹¹, 38¹¹¹, 39¹¹¹ respectively and that all these sets of trunks are connected to all of the primary trunk finders 18¹, 19¹, 20¹ and 18¹¹¹, 19¹¹¹, 20¹¹¹ and 18¹¹¹, 19¹¹¹,

20¹¹¹ respectively. The primary trunk finders are arranged so that all the idle finders of a selected group, e. g. 18¹¹¹, 19¹¹¹, 20¹¹¹ of the third group are caused to move together as soon as a group selector, e. g. 13¹ 70 is set onto a desired group. The setting of the group selector 13¹ will thus cause the primary trunk finders 18¹¹¹, 19¹¹¹, 20¹¹¹ to start hunting and these finders will then continue to move until one of them finds an idle trunk, 37¹, 38¹ or 39¹ that leads to the calling group. The primary trunk finders are so arranged that they only test such primary trunks as lead to a group in which there is a calling line waiting for extension 75 80 to a desired group. Thus if there are no group selectors 13¹¹¹, 14¹¹¹—13¹¹¹, 14¹¹¹—in the second and third groups that have been caused to select the group of primary trunk finders 18¹¹¹, 19¹¹¹, 20¹¹¹ these finders will 85 only test the trunks 37¹, 38¹ and 39¹. The moment one of these finders, e. g. 19¹¹¹ finds an idle trunk, e. g. 38¹, it stops and the secondary trunk finder 16¹, which belongs to the trunk 38¹ is now started and 90 moves its brushes onto the secondary trunk that is connected to the calling line connector, 5¹, which has connected to the calling line 2¹. All the primary trunk finders except the one 19¹¹¹ which found the free 95 trunk 38¹ continue moving until they regain their normal positions, where they stop until they are started again by another call.

The secondary trunk finders 15¹, 16¹, 17¹—15¹¹¹, 16¹¹¹, 17¹¹¹—15¹¹¹, 16¹¹¹, 17¹¹¹ are arranged so that they always find the proper secondary trunk from which the call came that was passed on to them, so that wrong connections in the case of several calls being simultaneously passed to different groups 100 105 are prevented with certainty. This means for preventing wrong connections is explained in subsequent paragraphs.

After a primary trunk finder 19¹¹¹ and a secondary trunk finder 16¹ have operated in the manner described, the calling subscriber 2¹ will be connected through 5¹, 16¹, 41¹, 38¹, 19¹¹¹, to the final trunk 44¹¹¹. The wanted-line-selector-connectors 24¹¹¹, 25¹¹¹ will then be started and an idle wanted-line-selector, 110 e. g. 27¹¹¹, will be connected by its connector 25¹¹¹ to the trunk 44¹¹¹. The calling subscriber 2¹ now sends his selecting impulses through 5¹, 32¹, 16¹, 41¹, 38¹, 19¹¹¹, 25¹¹¹ to the selector 27¹¹¹ of the selected group and sets this selector onto the line 303 of the wanted subscriber 3¹¹¹. As soon as this is done the "wanted-line-connector" 29¹¹¹ associated with 44¹¹¹ is started and its movable contacts travel until they reach the wanted line that has been designated by the selector 27¹¹¹ where they stop. Identifying means are provided for preventing wrong connections in case two or more connectors are started at the same time.

A ringing current is now sent from the wanted line connector 29^{III} to the wanted subscriber 3^{III}. When the wanted line connector connects to the wanted subscriber the 5 wanted line selector connector and the wanted line selector are restored to their normal positions. The ringing current is sent automatically from the connector 29^{III} to the wanted subscriber until this subscriber 10 responds. When the wanted subscriber raises his receiver from the hook, the ringing current is stopped and the talking connection is recorded by a current path that traverses the connector and which is independent of the wanted line selector 15 27^{III}.

At the end of the conversation the trunk finder 19^{III} is restored to its normal position. The calling line connector 5^I the wanted line connector 29^{III} and the trunk finder 16^I are 20 not restored to definite normal positions, although they could be so arranged.

It will be seen from Fig. 1 that from each of the primary trunk finders of each group 18^I, 19^I, 20^I—18^{II}, 19^{II}, 20^{II}—18^{III}, 19^{III}, 20^{III} one trunk leads to any one calling group. From the finder 18^I of the first group, for example only one trunk 37^I, 40^I, leads to the finder 17^I of the first group; from the finder 19^I only one trunk 38^I, 41^I, 30 leads to the finder 16^I of the first group and from the finder 20^I only one trunk 39^I, 42^I leads to the finder 15^I of the first group. The primary trunk finders of the other groups are similarly each provided with 35 only one trunk to each of the different calling groups. Hence it will be clear that if a primary trunk finder e. g. 18^{III}, finds that its trunk e. g. 37^I, that leads to a certain calling group is engaged, a connection between the group of this primary finder and the particular calling group will only be possible through other finders 19^{III}, 20^{III} of the same called group. For this reason it is important that when a call is passed on to 40 a certain wanted group several primary finders are started simultaneously; should one finder be unable to take up the call on account of its trunk being engaged, some other trunk finder will take it up whose 45 trunk is disengaged. The primary trunks will preferably be so connected to the primary trunk finders that the trunk finders of a group, e. g. 18^{III}, 19^{III}, 20^{III} will not simultaneously reach a plurality of trunks leading to the same calling group, e. g. the trunks 37^I, 38^I, 39^I but that the finders will reach such trunks one after the other. In order that the brushes of these finders are each at a different distance from the said 50 trunks when they are started these finders are preferably arranged to start from a definite normal position.

In Fig. 1 a system is outlined in which only one group selecting function occurs in 55 the establishing of each connection between

two subscribers and which would be suitable for comparatively small exchanges having a capacity for say 1000 lines.

In Figs. 2 and 3 a system is shown that would be suitable for 10000 lines and in 70 which two group selecting functions occur in the establishing of a connection between two subscribers.

The subscribers' stations are shown in Fig. 2 at the left and are marked with the reference signs CS. The stations that have the exponent "1" associated with the letter C of their reference signs belong to the first major group or to the first thousand, the stations with the exponent "2" belong to the 75 second thousand and so forth. Each major group or thousand group is composed of a plurality of minor groups or hundred groups. The signs of reference of the subscribers' and switches of the first hundred group in each thousand group have an index "I" appended to them, whilst the corresponding parts of the second and third hundred groups in Fig. 2 are denoted by the indexes "II" and "III." For calls or connections that originate in the first thousand group and that are to be extended to, or to be established with, other subscribers of the first thousand group, a group of primary trunk finders $P^1 F^1_I - P^1 F^3_I$ is provided, 80 whilst a second group of primary trunk finders $P^1 F^1_{II} - P^1 F^3_{II}$ is provided for calls that originate in the second thousand group and that are to be extended to subscribers of the first thousand group. In this way 90 a special set of primary trunk finders is provided for connections from each different thousand to the subscribers of the first thousand, so that if the exchange comprises ten different thousand groups there will be 100 ten groups of primary trunk finders for calls that are extended to the subscribers of the first thousand group.

Similarly for calls to the second thousand group a special group of primary 110 trunk finders will also be provided for each different major or thousand group.

In Fig. 2 only two of these groups of switches $P^2 F^1_I - P^2 F^3_I$ and $P^2 F^1_{II} - P^2 F^3_{II}$ are indicated. The various groups of primary trunk finders that extend the connections from the different thousand groups to certain thousand groups are each connected by sets of trunks to further groups of switches by means of which the desired minor or hundred group in the selected thousand is selected. Thus the two illustrated groups of primary trunk finders that extend connections to the second thousand group are connected by the sets of trunks $2S^2 T^1_I$ to $2S^2 T^3_I - 2S^2 T^1_{II}$ to $2S^2 T^3_{II}$, Fig. 3, to the bank contacts of trunk finders $2S^2 F^1_I$, $2S^2 F^3_I - 2S^2 F^1_{II}$, $2S^2 F^2_{II}$, $2S^2 F^3_{II}$. The connections intended for the second thousand and that originate in the first thousand 130

group are extended through the group of trunk finders $2S^2F^1_{II}$, $2S^2F^2_{II}$, $2S^2F^3_{II}$, whilst the connections intended for the second thousand group that originate in the second thousand group are extended through the group of switches $2S^2F^1_{III}$, $2S^2F^2_{III}$, $2S^2F^3_{III}$. Calls originating in the various thousand groups and that are extended to the first hundred of the second thousand are established by the group of trunk finders $2P^2F^1_{II}$, $2P^2F^2_{II}$, $2P^2F^3_{II}$, whilst the calls to the second or third hundred group of the second thousand pass through the finder groups $2P^2F^1_{III}$, $2P^2F^2_{III}$, $2P^2F^3_{III}$ and $2P^2F^1_{III}$, $2P^2F^2_{III}$, $2P^2F^3_{III}$ respectively. From these latter finder groups sets of trunks $F^2T^1_{II}$, $F^2T^2_{II}$, $F^2T^3_{II}$ — $F^2T^1_{III}$, $F^2T^2_{III}$, $F^2T^3_{III}$ — $F^2T^1_{III}$, $F^2T^2_{III}$, $F^2T^3_{III}$ extend to the groups of connectors $2FS^1_{II}$ — $2FS^1_{III}$ — $2FS^1_{III}$, Fig. 2. The connectors FS and the quick acting finders FQ extend calls or connections in two directions.

To elucidate the path of a connection or call through a system for say 10000 lines according to Figs. 2 and 3 it will be assumed that a subscriber $C^1S^2_{II}$ in the second hundred group of the first thousand establishes a connection with a subscriber $C^2S^1_{III}$ of the third hundred of the second thousand.

The first thing that happens when the subscriber $C^1S^2_{II}$ removes his receiver from his switchhook is that an idle quick acting switch or finder, e. g. $1FQ^2_{II}$ places its movable contacts into connection with the calling line and connects this line through a calling line connector finder IQ^2_{II} and a group selector connector $S^1C^2_{II}$ to an idle group selector $G^1S^2_{II}$ similarly as explained in connection with Fig. 1. As the calling subscriber desires a connection with a subscriber of the second thousand he will send selecting impulses that cause the group selector $G^1S^2_{II}$ to move its wipers onto the selecting wire that leads to the second thousand and this in turn will cause the idle finders of finder group $P^2F^1_{II}$ — $P^2F^3_{II}$ to start hunting. This hunting action will continue until a free trunk e. g. $P^1T^2_{II}$, leading to the calling group is found by one of the finders $P^2F^2_{II}$, whereupon the secondary trunk finder $S^1F^2_{II}$ belonging to $P^1T^2_{II}$ will also start in search of the trunk $S^1T^2_{II}$ to which the calling subscriber $C^1S^2_{II}$ is connected. In the meantime the calling line connector $1FS^2_{II}$ will have moved its brushes onto the calling line $C^1S^2_{II}$ which was marked by the quick acting finder $1FQ^2_{II}$ and the seizure of the calling line by the connector $1FS^2_{II}$ will have resulted in the quick-acting finder being separated from the connection and being connected to some other idle calling line connector, e. g. $1FS^3_{II}$ which may be a two-way switch.

The moment the secondary trunk finder $S^1F^2_{II}$ finds the secondary trunk $S^1T^2_{II}$ to

which the calling subscriber $C^1S^2_{II}$ is connected, the group selector $G^1S^2_{II}$ will be connected by its group selector connector $S^1C^2_{II}$ to a trunk e. g. $S^1T^3_{II}$ which has been seized by a calling line connector finder e. g. $1Q^2_{II}$. 70

The calling subscriber $C^1S^2_{II}$ is now connected through $1FS^2_{II}$, $S^1T^2_{II}$, $S^1F^2_{II}$, $P^1T^2_{II}$, $P^2F^2_{II}$, $2S^2T^2_{II}$ to the fixed contacts of the group of finders $2S^2F^1_{II}$, $2S^2F^2_{II}$, $2S^2F^3_{II}$. An idle second group selector, e. g. $2G^2S^1_{II}$, 75 will now be connected by its group selector connector $2S^2C^2_{II}$ to the trunk $2S^2T^2_{II}$. The calling subscriber then sends his hundreds selecting impulses into the group selector $2G^2S^1_{II}$ and causes the selector to place its movable contacts into connection with the selecting wire $2SW_{III}$ that leads to the desired hundred group. This results in the starting of the free finders of this group, e. g. $2P^2F^1_{III}$, $2P^2F^3_{III}$. The moment one of 80 these finders, e. g. $2P^2F^3_{III}$, finds a free trunk $2P^1T^3_{II}$, the finder $2S^2F^3_{II}$ belonging to this trunk is started and caused to make connection with the trunk $2S^2T^2_{II}$. When the trunks $2S^2T^2_{II}$ is thus extended to the 90 trunk $F^2T^3_{III}$ the group selector $2G^2S^1_{II}$ is separated from the connection by its connector $2S^2C^2_{II}$ and reverts to common use. The calling subscriber $C^1S^2_{II}$ is now connected through $1FS^2_{II}$, $S^1T^2_{II}$, $S^1F^2_{II}$, $P^2F^2_{II}$, 95 $2S^2T^2_{II}$, $2S^2F^3_{II}$, $2P^1T^3_{II}$, $2P^2F^3_{III}$ to the trunk $F^2T^3_{III}$ which leads to the third hundred group of the second thousand and thus also to the fixed contacts of the calling line connector finders $2Q^1_{III}$, $2Q^2_{III}$. The 100 calling line connector finders are so arranged that those that do not happen to be engaged for calls that have originated in the selected group are started hunting and continue moving until a quick-acting finder, 105 e. g. $2FQ^2_{III}$, is connected by its calling line connector finder to the trunk $F^2T^3_{III}$. Circuit changes now take place in the quick-acting finder $2FQ^2_{III}$ which cause it to act as a wanted line selector. The calling subscriber now sends selecting impulses into the compound selector switch $2FQ^2_{III}$, which acts both as a quick-acting finder and as a wanted line selector, and this selects the wanted line $C^2S^1_{III}$, whereupon the calling line connector $2FS^2_{III}$ — $2FS^3_{III}$ makes connection with the wanted line marked by the switch $2FQ^2_{III}$ so that the calling line connector $2FS^2_{III}$, on account of its acting also as a wanted line connector, may be called a 110 two-way connector or compound connector switch. When the two-way connector $2FS^2_{III}$ has made connection with the wanted line the compound selector switch $2FQ^2_{III}$ is separated from the connection 115 and reverts to common use, and a ringing current is sent to the wanted station $C^2S^1_{III}$ from the two-way connector $2FS^3_{III}$. When the called subscriber responds the ringing current is stopped, the connection is re- 120 125 130

corded by a recording device and the connection between the calling and called subscribers is then established as follows:— from $C^1S^2_{II}$ through $1FS^2_{II}$, $S^1T^2_{II}$, $S^1F^2_{II}$, 5 $P^1T^2_{II}$, $P^2F^2_{I}$, $2S^2T^2_{I}$, $2S^2F^3_{I}$, $2P^1T^3_{I}$, $2P^2F^3_{III}$, $F^2T^3_{III}$, $2FS^3_{III}$, to $C^2S^1_{III}$.

When the called subscriber replaces his receiver at the end of the conversation the primary trunk finders $P^2F^2_{I}$ and $2P^2F^3_{III}$ 10 that were used for the connection are restored to their normal positions. The connection is also broken in the switches $1FS^2_{II}$, $S^1F^2_{II}$ and $2S^2F^3_{I}$ but these are not restored to definite normal positions. When 15 the called subscriber replaces his receiver the connection is also interrupted in the compound connector switch $2FS^3_{III}$.

If the called subscriber $C^2S^1_{III}$ is the first to replace his receiver the connection is first 20 broken in the compound connector switch $2FS^3_{III}$ and in the secondary trunk finders $2S^2F^3_{I}$, $S^1F^2_{II}$ and the primary trunk finders $P^2F^2_{I}$ and $2P^2F^3_{III}$ are simultaneously restored to their normal positions. Upon the 25 calling subscriber replacing his receiver the connection is also interrupted in the compound connector switch $1FS^2_{II}$.

In an exchange or system for 100000 subscribers ten groups are formed for 10000 30 subscribers each and each of these groups is divided into ten minor groups for 1000 subscribers each. Each minor group is divided into ten sub-groups each having 100 subscribers and ten trunk finders. In Figs. 35 4 and 5 a system for 100000 subscribers is represented. In the first major group of 10000 two minor groups I, II for 1000 lines each and in the second major group two other minor groups XI, XII are illustrated. 40 The ten different hundred groups of the first thousand are each provided with a set of trunk finders 1, 1, 1—1¹, 1¹, 1¹—1², 1², 1² and the ten different hundred groups of the second thousand are similarly provided 45 with ten sets of trunk finders 2, 2, 2—2¹, 2¹, 2¹—2², 2², 2². In the same way each of the hundred groups in the second ten thousand group and in the other ten thousand groups has a set of finders 11, 11, 11—11¹, 11¹, 11¹ 50 etc. Each set of finders 1, 1, 1, is connected to a set of trunks, e. g. 14, to which are connected the bank contacts of sets of finders 17, 17, 17—18, 18, 18, each of these sets leading to a different ten thousand group. Each set, e. g. 17, 17, 17 is connected by a set of trunks, e. g. 19, 19, 19, to the fixed contacts of another set of finders 20, 20, 20 in the particular ten thousand group. Each of these other sets of 55 finders 20, 20, 20 is connected to a set of trunks 21 that are joined to the fixed contacts of finder groups 22, 22, 22—23, 23, 23 each of which leads to a different thousand group. Each of the finder groups 22, 22, 22 60 etc. is connected to a further set of finders 65

24, 24, 24 that is connected to a set of trunks 25 which in turn is joined in multiple to the fixed contacts of sets of finders 26, 26, 26—27, 27, 27—28, 28, 28. Each of the sets of finders 26, 26, 26—27, 27, 27—28, 70 28, 28 belongs to a different hundred group of its thousand and is connected to trunks, e. g. 29, that lead to the connectors 30, 30, 30 of a certain hundred.

The sets of finders 1, 1, 1—20, 20, 20—24, 75 24, 24 are secondary trunk finders in the sense of Fig. 1 and the sets of finders 17, 17, 17—22, 22, 22—26, 26, 26 are primary trunk finders in this sense. Associated 80 with each set of primary trunk finders is a set of group selectors 31, 31 although all the group selectors are not represented in the drawing. The general connecting path in establishing connections between two subscribers in a system for 100000 subscribers will be readily traced with the aid of Figs. 4 and 5 without further explanation.

It will be clear from Figs. 4 and 5 that the number of sets of finders 17, 17, 17—18, 18, 18 provided for each thousand group will be equal to the number of major groups or ten-thousand-groups that may be selected by the thousand group. Thus in an exchange for 100000 subscribers ten such sets of finders will be provided for each thousand, this making one hundred sets of these finders for each ten thousand group. For selecting the various thousand groups of a ten thousand group each ten thousand group has ten sets of finders 22, 22, 22—23, 23, 23. For the calls coming from the various ten thousand groups there will be in each ten thousand group altogether 100 of these latter sets of finders. Finally each thousand group has ten sets of finders such as 26, 26, 26—27, 27, 27—28, 28, 28 for connections with the different hundred groups of the particular thousand.

It having now been explained how an exchange for 1000 lines may be extended to 110 10000 lines and how a 10000 line exchange may be increased for a capacity of 100000 lines, further extensions will be understood without additional description.

The circuit details of a system according 115 to Fig. 1 will now be described. These details are illustrated in Figs. 6 to 13.

In Fig. 6 the quick-acting finders RI, RII and "calling line connectors" VI, VII of a hundred group are shown. Fig. 7 shows the 120 calling-line connector-finders VSI, VSII, Fig. 7^a the group selectors GWI, GWII and the group-selector-connectors GVI, GVII of a hundred group.

In Fig. 8 three secondary trunk finders 125 ZVI, ZVII, ZVIII of a hundred group and in Fig. 9 three primary trunk finders EVI, EVII, EVIII, are illustrated.

LWI, LWII in Fig. 10 represent two wanted line selectors of a hundred group, 130

LVI, LVII are two wanted-line-selector connectors and SV is a wanted-line-connector.

5 Figs. 11 and 12 illustrate a set of secondary trunk finders Zv1, Zv3, Zv3 and a set of primary trunk finders Ev1, Ev2, Ev3 that belong to a second hundred group.

10 The operation of the various switches shown in Figs. 6 to 12 will be understood 10 from the following detail description of a connection between a calling and called subscriber.

15 Each subscriber T is connected to the exchange by two wires 11, 12 and has three wires 1, 2, 3 in the exchange by which his line and cut-off relay 16 is connected to the fixed contacts of calling line connectors VI, VII and of wanted line connectors SV of his hundred group. The wire 3 that leads to 20 the cut-off relay 16 is also connected to the quick-acting finders RI, RII and to the wanted line selectors LWI, LWII, Fig. 10. Each subscriber T has a conversation recorder 17 which is connected by a wire 4 to 25 the contacts of the calling line connectors VI, VII. Three additional wires 5, 6, 7 are provided for each subscriber in the exchange which are multiply connected to the contacts of the quick-acting finders of the 30 subscribers' hundred group. Finally each subscriber has two identifying wires 8, 9 or as many identifying wires as there are quick-acting finders in his hundred group. Each identifying wire leads to one quick- 35 acting finder only but is connected in multiple to the contacts of the calling line connectors.

40 When a group selector GWI or GWII has been caused to select a desired group the primary trunk finders EVI, EVII, EVIII in the selected group are made to hunt for 45 an idle primary trunk E^1_1, E^1_2, E^1_3 leading to the calling group. When an idle trunk has been found the secondary trunk finder, 50 e. g. ZVII, belonging thereto is set in motion and caused to find the secondary trunk, e. g. Z² to which the calling subscriber is already connected.

55 Each of the trunks E^1_1, E^1_2, E^1_3 of every hundred group is connected to a set of bank contacts of a primary trunk finder in each of the different hundred groups as indicated in Fig. 1.

It will now be assumed that a subscriber 55 T establishes a connection with the subscriber No. 134.

60 When the calling subscriber T removes his receiver from its hook a current flows from earth through a relay 14, which is common to all the subscribers of the calling subscribers' hundred group, through the bus bar 16¹, thence through 10, 18, 12, T, 11, 20, 21 to the negative pole of the exchange battery. The common relay 14 is energized 65 and its armature contact closes the circuits

of the motor magnets 22 and 23 of the quick-acting finders RI and RII. The current through the magnet 22 flows from the earth through 15, 24, 25, 22, 26, 29 interrupter 28 to the negative pole, whilst the impulses through the motor magnet 23 flow from the earth through 15, 24, 23, 27, interrupter 28 to the negative pole. It will be seen that at a moment when the magnet 23 receives a current impulse the other motor 70 magnet 22 will be deenergized. By this means the movable contacts or brushes of the one quick-acting finder RI are always caused 75 to reach new sets of contacts before these sets can be reached by the brushes of the other quick-acting finder. Hence it will not happen that two quick-acting finders are set 80 onto the bank contacts of the same subgroup of subscribers' lines at the same instant and that one and the same subscriber's 85 line is hereby extended to two different trunks ZI, ZII.

The quick-acting finder RI has a group test relay 30 and the quick-acting finder RII is equipped with a similar group test relay 31. The quick-acting finders are also each equipped with a set of individual test relays 32, 33, 34 and 35, 36, 37 respectively. At each new current impulse through the motor magnets of the quick-acting finders 95 the sets of brushes $e_1, s_1, t_1, a_1, b_1-c_2, s_2, t_2, a_2, b_2-c_3, s_3, t_3, a_3, b_3$ and $e_4, s_4, t_4, a_4, b_4-c_5, s_5, t_5, a_5, b_5-c_6, s_6, t_6, a_6, b_6$ respectively are moved onto another group of three subscribers and at each step 100 the brushes s_1, s_2, s_3 and s_4, s_5, s_6 test three different subscribers' lines in order to ascertain 105 whether they are in a calling condition. The moment a test brush, e. g. s_1 , reaches the wire 38 of a calling line a current flows through the group test relay 30 of the particular quick-acting finder which may be traced from the negative pole through 39, 40, 41, 30, 42, $s_1, 38, 20, 11, T, 12, 18, 16^1, 14$ to earth. The group test 110 relay 30 is energized and opens the circuit of the motor magnet 22 at 25 so that the brush sets of the finder RI stop travelling. At the same time the contacts 42, 43, 44 are opened so as to disconnect the branch 115 circuits from the test brushes s_1, s_2, s_3 . By contact 45 a locking circuit is closed for the group test relay 30. By the closure of contact 46 the group test relay causes the energization of a relay 50 and this relay 120 then opens its contact 24 and thus interrupts the circuit of the motor magnet 23 of the second quick-acting finder, so that the second quick-acting finder is stopped even if other subscribers happen to be calling at 125 that moment. This stopping of the second quick-acting finder lasts until the calling subscriber T is extended by quick-acting finder RI to a trunk in the manner presently described. In this way the danger is avoided 130

ed of a brush of the second quick-acting finder being also moved onto the line of the calling subscriber T at the next step or one of the subsequent steps taken by the 6 second finder RII before the said subscriber's line is extended through the first finder RI and before the calling condition is removed from this line. The extension of a calling line after it has been found by a 10 quick-acting finder takes place almost immediately so that the stoppage of the second quick-acting finder only lasts a fraction of a second.

By its contact 51 the group test relay 30 15 connects earth to the relay 54 whilst the negative pole of the battery is connected through the contacts 52 and 48 and through the interrupter 28 alternatively to the wires 57, 58. Upon the closure of the contacts 20 51, 52 and 48 a current impulse first flows through the relay 54 and then further impulses flow through the relays 55, 56 in succession. The first impulse that flows through the relay 54 may be traced from 25 the negative pole through 28, 26, 52, 59, 54, 51 to earth. This energizes the relay 54 and causes it to close a locking circuit for itself that extends from the negative pole through 60, 51 to earth. By the 30 energization of the relay 54 a circuit through 55 is prepared at the contact 61 and as soon as the interrupter 28 connects the negative pole to the wire 27 a current flows from the negative pole through 28, 27, 48, 62, 55, 61 to earth. This energizes the relay 55 which closes a locking circuit for itself that extends from the earth through 61, 55, 63 to the negative pole. An energizing circuit is then prepared at contact 64 for the relay 56 and as soon as the interrupter 28 connects the negative pole to the wire 29 a current flows from the negative pole through 29, 26, 52, 67, 64 to earth. This energizes the relay 56 which closes an 40 own locking circuit extending from the negative pole through 68, 56, 64 to earth. The energizations of the relays 54, 55, 56 in rapid succession in the manner described causes the negative pole to be connected in 45 rapid succession through a contact 53 to the test wires 69, 70 and 71. When the relay 54 is energized the application of the negative pole takes places through 53, 73, 66, 69 and upon the energization of the relay 55 the negative pole is applied through 53, 73, 65 to 70, and finally when the relay 56 is energized the negative pole is connected 55 through 53, 72 to the wire 71.

It will thus be seen from the preceding 60 paragraphs that when the group test relay 30 is energized the negative pole is connected at rapidly succeeding intervals to the test coils 74, 75 and 76. But the application of the negative pole to all of these 65 coils will only happen if the third set of

brushes, or the test brush s_3 , happens to strike the contacts of the calling line. If it were the test brush s_2 of the second set of brushes that struck the calling line only the two relays 54, 55 would be energized. 70 But if test brush s_1 of the first set of brushes strikes the calling line the energizations of the chain of relays 54, 55, 56 will be stopped immediately the first relay 54 is excited. This is accomplished by the simultaneous energization of a relay 77 at the moment a relay 32, 33 or 34 is excited this causing the opening of the circuit of relay 30 at the contact 39 and the interruption of the current impulses at 52 and 48 that flow from the interrupter 28 to the relays 54, 55 and 56. 75

The moment the relay 54 is energized as previously described an initial test current path is closed extending from the negative pole through 53, 73, 66, winding 74 of the individual test relay 32, contact 78, brush s_1 , to the test wire 38. If the subscriber to whom the test wire 38 belongs happens to be calling the test current path just traced 80 will extend further through 20, 11, 1, 12, 18, 16¹, common relay 14 to earth and the test relay 32 will be energized. This relay then closes the contacts 79, 80, 81 and 82. By the closure of contact 79 a new circuit is 85 completed which extends from earth through 83, Fig. 7, 77, upper winding of relay 32, 79, 1¹, 84, cut off relay 16 to the negative pole. The relay 77 is energized and at its contact 39 it opens the circuit of the group test relay 30 so that this relay lets its armature drop back and prevents the energizations of the relays 55 and 56 and the applications of the negative pole to the relays 33 and 34 through 53. If the test 90 brush s_2 of the second set of brushes had struck the calling line the relay 33 would have been energized in series with the relay 77 and energizations of the relays 54, 55, 56 would have progressed until the second relay 95 55 was energized.

The energization of the relays 77 and 32 is accompanied by the energization of the cut-off relay or line extending relay 16, and the calling line 11, 12 is thus extended to 100 the brushes, a^1 , b^1 of the connector finder VSI, the path from 11 being through 85, 86, a^1 , 81, 87 to a^1 and from 12 through 19, 91, b^1 , 82, 88 to b^1 .

At the moment the group test relay 30 110 was de-energized, the relay 50 was also de-energized by the opening of the contact 46, so that now, if other subscribers happen to be calling and to be energizing the common 115 relay 14, current impulses will flow from the negative pole through the interrupter 28 and through 27 to the motor magnet 23 of the second quick-acting finder. This finder will then again commence moving its 120 brushes until one or several of them strike 125

upon a calling line or lines. The group test relay 31 will then be energized and will stop the operation of the motor magnet and the lines that the sets of brushes are contacting 5 with will be tested one after the other by the relays 91, 92, 93 and 35, 36, 37 until an individual calling line has been found. By the described arrangement of the quick-acting finders RI, RII according to which the 10 brush sets of the various finders are each caused to reach a group of subscribers before this same group can be reached by the brushes of another finder and by which the individual lines upon which the brush sets 15 of a finder stop are tested one after the other, the danger is obviated of one and the same calling line being extended to two different connector finders and of several calling lines being extended through one quick- 20 acting finder to the same connector finder.

The danger of several calling lines being extended through the various brush sets of one and the same quick-acting finder to the same numerical switch or to the same connector 25 finder may also be prevented by arranging the circuits of the locking windings of the test relays in such a manner that any test relay of the series cuts off the battery connection from the locking windings 30 of the following test relays in the series. With this arrangement the energization of the first test relay of the series would prevent the energization of the locking winding of the second and any succeeding relays. 35 The energization of the second test relay would prevent the energization of the locking winding of the third and any succeeding relays and so forth. This can be accomplished by providing each test relay with 40 an extra front and back contact, by connecting the movable contact spring of the one test relay to the fixed contact of the next and by connecting the movable spring of each relay that is normally insulated to the locking winding of its particular relay. 45 With test relays arranged in this manner the extra set of relays by which the test potential is applied to the test relays one after the other may be omitted.

50 As soon as the calling subscriber T is extended in the manner described to a calling line connector finder VSI an impulse relay, e. g. 94, in a group selector is energized. It has already been mentioned that each time a 55 quick-acting finder has completed its functions in connection with a call it is immediately connected by its calling line connector-finder to another idle calling line connector, or to the trunk belonging to this connector and that a group selector is thereupon 60 also connected to this connector or trunk. The circuits and devices for accomplishing this will be explained later. For the time being it may be assumed that the brushes 65 of the connector-finder VSI and those of

the group selector connector GVII have seized the second trunk Z2 or the calling line connector VII. This being so a current will flow, when the calling line 11, 12 is extended as described, from the 70 negative pole of the battery through 94, 95, 101, 102, 111, 112, a7, 87, 81, a1, 85, 11, T, 12, 19, 91, b1, 82, 88, b7, 113, 114 to earth. The calling subscriber is thus 75 connected to the group selector GWII and as he desires a connection with the subscriber No. 134 he will cause his impulse transmitter to produce a single interruption of the circuit of the relay 94 in order to 80 select the first hundred group. Since the relay 115 is energized by a circuit extending from earth through 49, Fig. 6, 289, 119, 120, 121, 110, 99, 115, 118 to the negative pole and as the contact 116 is thus closed, each 85 interruption of the current flowing through the relay 94 will result in a current impulse flowing from the earth through 49, 119, 120, 121, 110, 99, 123, 116, motor magnet 124 of the group selector to the negative pole. At each impulse the brushes 125, 126, 127, 128 of the group selector GWII are moved a 90 step forwards onto another set of fixed contacts. As the desired number in this case is No. 134 the calling subscriber causes only one interruption of the current flowing 95 through the relay 94 so as to shift the brushes 125, 126, 127, 128 one step forwards onto the selecting wires leading to the first hundred group. These selecting wires comprise the wires 129, 130, 131, 132 and 132'. 100 After the calling subscriber has caused the brushes of the group selector to select the desired group as described an interval ensues during which the change-over relay 122 is steadily short-circuited by the contact 105 118 so that it allows its armature to drop back and close the contacts 134, 135, 136, 137 and 138. Current impulses then flow from earth through the interrupter, 139, 134, 235, 125, 129, Figs. 8 and 9, 141, 142, 110 143 through the contacts 144, 145, 146 and through the motor magnets 147, 148, 149 of the primary trunk finders EVI, EVII, EVIII of the first hundred group. Simultaneously with the sending of current impulses through the motor magnets 147, 148, 149, the positive battery pole is applied to the contacts 153, 154, 155 of the primary trunk finders EVI, EVII, EVIII and the negative pole is applied to 150, 151, 152. 115 These contacts correspond to the first hundred group of subscribers. If the call had come from the second hundred group the energizations of the motor magnets 147, 148, 149 would have been accompanied by the 120 connection of the negative pole to the contacts 156, 157, 158 and of the positive pole to the contacts 159, 160, 161. When calls proceed from the third hundred group the negative pole is connected to the contacts 130

162, 163, 164 and the positive pole to the contacts 165, 166, 167. By this means the primary trunk finders are always caused to test only the particular set of primary trunks that leads to the group of the calling subscriber. No testing operations occur when the brushes of the primary trunk finders wipe over the contacts of trunks that lead to noncalling groups, so that these finders never stop upon trunks which lead to a non-calling group. Thus the primary trunk finders possess the faculty of distinguishing between trunks that lead to calling groups and non-calling groups.

15 The application of the negative pole to the contacts 150, 151, 152 takes place when the change over relay 122 is deenergized as described and the path through which the negative pole is connected may be traced 20 from the negative pole through 137, 168, Fig. 7^a, 128, 130 to the contacts 150, 151, 152, whilst the application of the positive pole takes place over a path extending from the earth through 169, 138, 138¹, Fig. 8 resistances 170, 171, 172, through the contacts 174, 178, 182 and through the wires 185, 186 and 187. The primary trunk finders EVI, EVII, EVIII whose motor magnets 147, 148, 149 are energized by current impulses from 25 the interrupter 139, Fig. 7, and which are each equipped with a front set of seven brushes and a rear set of four brushes, now move their brushes over their fixed contact sets. The front and rear sets of brushes reach 30 opposite sets of fixed contact sets simultaneously. Thus the front set of brushes of EVI passes over the front contacts 190, 191, 192, 193, 194, 195, 153 whilst the corresponding rear set of brushes wipes across 35 the contacts 150, 196, 197, 198. The brush sets of the various primary trunk finders of each group occupy different positions with respect to the primary trunks of each group, so that the brushes of a group of 40 finders reach the primary trunks of a trunk group one after the other. Thus the primary trunk finder EVI will reach the primary trunk E¹, that leads to calling group and at the next step taken by the finders 45 50 55 60 65 70 75 80 85 90 95 100 105 110 115 120 125 130

155 that correspond to the calling group are connected to the negative and positive battery poles respectively. It will be assumed that the primary trunk E¹, is busy. When the test brushes 204 and 203 reach 70 their corresponding contacts 153 and 150 respectively a test current flows from the contact 150 that is connected to the negative pole through 205, 206, test relay 200, test brush 204, to the contact 153 that is connected to the positive pole. But as the first primary trunk E¹, is busy the potential on the test contact 153 will be so low that the test relay 200 will not be energized. The primary trunk finder EVI will therefore 80 continue moving its brushes reaching the primary trunks leading to the second, third, fourth and other hundred groups of the exchange one after the other. After the brushes of the first primary trunk finder 85 EVI have passed the contact set of the primary trunk E¹, the brushes 207, 208, 209, 210, 211, 212, 213 will reach the contacts 154, 214, 215, 216, 217, 218, 219 of the trunk E². It will be assumed that this trunk is 90 idle. A current will flow from the contact 151 that is connected to the negative pole through 220, 224, test relay 201, test brush 207, test contact 154, 186, 178 resistance 171, 138¹, 138, 169 to earth or to the positive pole. 95 This current will energize the relay 201 because the potential on the test contact of the idle trunk will be high enough to do so. The relay 201 opens the circuit of the motor magnet 148 at 145 so that the brushes of the primary trunk finder are stopped. By its contact 228 it closes a circuit that extends from the negative pole through 228, 221, 131, 127, 232, relay 234, 136 to the positive pole. The current in this circuit energizes the relay 234 and causes it to close a locking circuit for itself that extends from the negative pole through 136, 234, 236 to the positive pole of the battery. At its contact 235 the relay 234 opens the path of the current 100 impulses from the interrupter 139 through 134, 235, 125 to the wire 129 so that the motor magnets of the primary trunk finders EVI, EVII, EVIII can no longer be energized through this current path. By opening its contact 168 the relay 234 also 105 interrupts the connection between the negative pole and the wire 130 and the contacts 150, 151, 152 so that after the primary trunk finder EVII has seized an idle primary 110 trunk, no further tests of primary trunks leading to the calling group will be executed by the other trunk finders. These other trunk finders EVI, EVIII now receive 115 moving impulses from an interrupter 236¹ 120 to the lead 237 of which their motor magnets are connected by their auxiliary switches 238, 239 the moment their brushes are moved away from their normal positions. As soon as these brushes regain their 125 130

It has already been explained that at the moment the primary trunk finders are started the contacts 150, 151, 152 and 153, 154,

normal positions the switches 238, 239 break the connections between the motor magnets 147, 149 and the wire 237 and re-establish their connections with the wire 131. But as this wire is disconnected from the interrupter 139, Fig. 7^a, the motor magnets 147, 149 will not receive further impulses and the primary trunk finders EVI, EVII will remain in their normal positions.

- 10 The test relay 201 of the primary trunk finder EVII that has seized the trunk E¹, completes a circuit by its contact 231 that extends from the negative pole of the battery through 239, 231, 212, 244, motor magnet 15 net 238 of the secondary trunk finder ZVII to earth. By this means the brushes 246, 247, 248, 249, 250, 251, 252 are set in motion and this motion continues until the brushes of this secondary trunk finder reach the secondary trunk ZII to which the particular calling subscriber is connected (through the quick-acting finder RI or through the calling line connector VII) whose call was passed in the manner described above 20 through the group selector GWII and through the primary trunk finder EVII to the secondary trunk finder ZVII. An identifying means is provided by which the secondary trunk finder is able to pick out the correct calling line amongst any number of calling lines. In other words a secondary trunk finder that is started moving as a result of a call from a certain subscriber will always move its brushes onto the trunk to 25 which this subscriber is connected but never onto any other trunk which might also happen to be connected to a calling subscriber. The identifying means by which this is accomplished includes the identifying wires 30 132, 132¹—253, 253¹ Figs. 7 and 8—254, 254¹. Each group selector has a separate identifying wire leading to each group of primary trunk finders. Thus the group selector GWI has its own identifying wire 132¹ leading 35 to the primary trunk finders EVI, EVII, EVIII and the group selector GWII also has its own identifying wire 132 leading to the first group of finders EVI, EVII, EVIII. A separate set of identifying wires 40 leads from the bank contacts of the secondary trunk finders ZVI, ZVII, ZVIII to each group selector connector GVI, GVII. Thus identifying wires 253, 254 are provided that lead only to the bank contacts of the 45 group selector connector GVII and there is a second set of identifying wires 253¹, 254¹ that leads from the banks contacts of the secondary trunk finders ZVI, ZVII, ZVIII only to the bank contacts of the group selector connector GVI. Only when a group selector GWII is set onto a set of selecting wires (129, 130, 131, 132, 132¹) the identifying wire 132 belonging to this set of wires is connected to the negative pole through 126, 50 135. At the same moment one of the iden-

tifying wires 253 or 254 that correspond to the group selector connector GVII will be connected to the positive pole through 100 and 95. If the group selector connector GVII is connected to the second trunk ZII 55 the wire 254 will be connected to the positive pole. Another important point is that the identifying relay 255 in the primary trunk finder is connected in such a way that it will, in the case of GVII having seized Z₂, only be excited and be caused to open the circuit of the motor magnet 238 of the secondary trunk finder ZVII if the one end of its winding is connected to the wire 132 and the other end to the wire 254. Thus as soon as 60 the brush 248 of the secondary trunk finder reaches the contact of the wire 254, a current flows from the negative pole through 135, 126, 132, 222 lower winding 255, 210, 216, 242, 179, 248, 254, 109, 100, 95 to earth. The identifying relay 255 is energized and 65 opens its contacts 224, 239 whilst closing its contacts 227, 226, 225 and 253. By closing its contacts 226, 227 the relay 255 completes a locking circuit for itself which at first extends from the negative pole through 226, upper winding of 255, 227, 207, 154, 186, 178, 138, 169 to earth. By closing contact 225 the relay 255 switches the relay 201 into a locking circuit which at first extends from the negative pole through 225, 201, 207, 154, 186, 178, 171, 138, 269 to earth. At the contact 239 the current which flows from the negative pole through 239, 231, 212, 218, 244, 238 and energizes the motor magnet 238 of the secondary trunk finder ZVII is interrupted so that the brushes of this finder stop on the contacts of the trunk ZII. At the same moment the closure of contact 253 completes a circuit that extends from the negative pole through 253, 213, 219, 245, 246, 256, 106, 102, relay 257 to earth. The relay 257 is energized and by closing its contact 258 it excites the differential relay 259. This 70 relay opens its contacts 95, 95¹ and closes its contacts 96, 98. By the closure of the contact 98 a locking circuit is completed for the relay 257 which extends from the earth through 257, 261, 98 to the negative pole. Through contact 96 a current is caused to flow from the negative pole through 96, the motor magnet 260, interrupter 139 to earth and this results in brushes of the group selector connector being set in motion. But, before this motion begins a circuit is completed by the closure of the contact 262 by relay 257 which extends from the earth through 262, 104, 105, 263, 249, 264, relay 265 to the negative pole, so that before the group selector connector is started the relay 265 is caused to open the contacts 180, 179, 178, 264 and to close the contacts 177, 265¹, 267. The relay 265 closes a locking circuit for itself, which includes 265¹, 250, 268, 269 and goes through 269¹ to earth, and from 75 80 85 90 95 100 105 110 115 120 125 130

that moment the locking circuits of the relays 255 and 201 Fig. 9 no longer extend through the contact 178 and resistance 171, and through 138, 169 to earth, but through 5 177, 250, 268, 269 to earth.

The line of the calling subscriber is now extended through the contacts 266 and 267 to the primary trunk finder EVII.

It must now be pointed out that at the 10 moment the line of the calling subscriber T was extended through the quick-acting finder RI to the "calling line connector finder" VS1, the relay 77, Fig. 6 was energized and completed the circuit of the motor magnet 270 of the calling line connector VII by its contact 49. The calling line connector was thus started in its operation of finding the calling line marked by the quick-acting finder or "calling line marking switch" 15 RI, before the calling subscriber commenced sending his selecting impulses to the group selector GWII. According to the position of the contact set in the contact bank of the calling line connector VII its brushes 20 will take a shorter or longer time to reach the calling subscriber's contacts. In some cases these brushes will reach the calling line before the selecting operation of the group selector is connected. But it may also 25 happen that the calling line connector reaches the calling line whilst the selecting operation of the group selector is progressing. The moment the brushes of the calling line connector reach the calling line the 30 connection of this line through the quick-acting finder is broken and is substituted by another connection through brushes of the calling line connector VII. Thus when the brushes c8, e7, e8, a7, b7, z7, reach the fixed 35 contacts of the calling subscriber a current flows from the negative pole through the identifying wire e9, Fig. 7 89, d7, identifying wire e10, upper winding of the identifying relay 271, brush e7, identifying wire 40 8, brush e1, 80 to the positive pole. The relay 271 is thus energized and at its contact 45 272 it opens the circuit of the motor magnet 270 causing the brushes of the calling line connector to stop. At the same moment a 50 circuit including the relay 279 is completed by contact 273 this circuit extending from the negative pole through 273, 279, 120, 119, 49 to the positive pole. The relay 279 opens its contact 276 and closes its contacts 55 274, 275, 277, 288. A new circuit is completed by contact 275 for the relay 279, this circuit extending from the negative pole through the cut-off relay 16 and 60 through 3, c8, 275, 120, 269 to the positive pole. A starting circuit for the calling line connector finder VS1 is closed by the contact 274 which may be traced from the negative pole through 274, 283, 280 right winding of the starting relay 283 to the 65 positive pole. The relay 283 is thus ener-

gized and closes its contacts 90, 284 whilst opening its contacts 285, 83, 286, 87, 88 and 70 89. Through contact 284 a new circuit is closed including the right winding of relay 283 which extends from the positive pole through 284, 281 287, 288 to the negative pole. At contact 90 the circuit of the motor magnet 289 is closed and also a circuit including the left winding of the relay 283. At each current impulse from the interrupter 291 the motor magnet 289 steps the brushes of the connector finder onto another set of contacts or onto another secondary trunk. These operations continue 75 until the brush 281 strikes a wire similar 80 to the wire 287 that has no connection with the negative pole.

The wires 287 of busy trunks, or of trunks that have already been seized by calling line connector finders, will be connected to the negative battery pole and this connection will be made either through a contact 288 of a release relay 114 or through a contact 286 of a starting relay. The moment the brush 284 of the connector finder finds an idle and unseized trunk and when the current impulse sent from the interrupter 291 and the left winding of the relay 283 ceases, the relay 283 lets its armature drop back and thus opens the circuit of the motor magnet 289 which results in the brushes of the calling line connector finder stopping on the contacts of an idle and unseized secondary trunk. When the relay 283 was energized the circuit including the relay 77, the upper winding of relay 32, contact 79 and the cut-off relay was opened, so that the relays 77 and 32 were de-energized. The cut-off relay 16, was however, not energized but is kept excited 105 by a current that flows from the earth through 269, 120, 279, 275, c8, 3, 16 to the negative pole. When the connector finder VS1 seizes an idle unseized trunk it connects the negative pole to the wire 293 or 110 293¹ through 289, 285, 282 and thus prepares a stopping circuit for started group selector connectors. When the brush 102 of a group selector connector reaches the contact of a wire 293¹ that is connected to the negative pole a current flows through the left winding of the differential relay 259 of the particular group selector connector. The circuit of the current will extend from the earth through the left winding of relay 259, 102, 107, 293, brush 282, contact 285, contact 289 to the negative pole. In order to prevent a continuous flow of current in this circuit a relay may be inserted between the contacts 285 and 289 which is energized 115 the moment this circuit is closed and which then opens the locking circuit of a second relay that was previously closed by the aid of relay 77. This second relay will then be deenergized and will open the connection 120 125 130 135 140 145 150 155 160 165 170 175 180

between the negative pole and the brush 282 so that other group selector connectors will not stop on a seized trunk.

The current that flows through the left winding of the differential relay 259 neutralizes the magnetization produced by the right winding so that the relay 259 lets its armature drop back. The locking circuit of the relay 257 and the circuit of the motor 10 magnet 260 are then opened at the contacts 98 and 96 respectively. The relay 257 is de-energized and opens the contacts 258, 261 and 262. The quick-acting finder RI is thus connected to an idle unseized secondary 15 trunk and the group selector connector that was started when the secondary trunk finder ZVII reached the secondary trunk to which the calling subscriber is connected, is caused to move its brushes onto the trunk seized by 20 the connector finder VSI.

The moment the relay 279 was energized a circuit was closed through the calling station T as follows: From earth through 114, 113, 278, b7, 2, 12, T, 11, 1, a7, 25 277, 112, 295, 269, 251, 266, 241, 215, 209, 300, 301 to the negative pole. This circuit is closed for a brief interval only and is opened the moment a free wanted line selector connector LV, Fig. 10 moves its 30 brushes onto the final trunk SVII.

When the brushes 207, 208, 209, 210, 211, 212, 213 of the primary trunk finder EVII seized the primary trunk E₁, the energization of the test relay 201 resulted in the 35 closure of a starting circuit for the idle line selector connectors LVI, LVII at contact 227. If both line selector connector are idle a current flows from the negative pole through 227, Fig. 9, 320, 321, contacts 324, 40 325, motor magnets 322, 323, contacts 326, 327 to earth. The magnets 322, 323 move the brush sets 338, 339, 340, 341, 342—343, 344, 345, 346, 347 over their bank contacts.

As soon as these brushes leave their normal 45 positions the magnets 322, 323 are switched by switches 350, 351 and through contacts 348, 349 into circuits that do not depend upon the starting circuit 321. The said magnets now cause their brushes to travel 50 over the contacts of the final trunks SV until a test brush 342 or 347 reaches the wire 353 that is connected by the contact 230 of the test relay 201 of the primary trunk finder EVII to earth. Assuming that the test 55 brush 342 reaches the wire 353 first, a current will flow from the negative pole through the test relay 354, 331, 342, 353, 354, 355, 330 to earth. The test relay 354 is energized and closes a locking circuit for 60 itself through 332 and 356¹. Through its contact 330¹ it also closes a circuit which extends from the earth through 330, 341, 357, 358, relay 359 to the negative pole and energizes the relay 359. This relay closes a 65 locking circuit for itself which extends from

the negative pole through 360, 207, 154, 186, 177, 250, 268, 269 to the positive pole. At contact 354¹ the relay 359 opens the test current path through the wire 353 so that other "wanted line selector connectors" 70 cannot seize the final trunk SVII. At its contact 300 the relay 359 severs the connection between the negative pole and the wire 360, but it simultaneously establishes a new connection between the negative pole and 75 the wire 361 through the contact 362, wire 363, brush 340, 329, 364, current impulse relay 365, negative pole of battery. The calling subscriber is now connected to the selecting impulse relay 365 of the wanted 80 line selector LWI and current flows through this relay and the calling station T through the following circuit: battery BI, 365, 364, 329, 340, 363, 362, 361, 209, 215, 241, 266, 251, 269, 295, 112, 277, a7, 1, 11, T, 12, 2, 85 b7, 278, 113, release control relay 114 to earth.

It must now be mentioned that after the wanted line selector connector LVI has seized the final trunk SVII to which the 90 calling subscriber is connected the other wanted line selector connectors LVII etc. either seize other calling final trunks or, if there are no other calling final trunks, are kept moving by their magnets 323 etc. until 95 the switch 351 opens the contact 349 and thus breaks the circuit of the magnet 323. This happens the moment the brushes 343, 344, 345, 346, 347 reach their normal position.

When the brushes 338, 339, 340, 341, 342 of the wanted line selector connector LVI left their normal position a contact 356 was closed by the switch 350 and a circuit completed from the earth through 356, contact 370, relay 371 to the negative pole. 105 This relay 371 was energized and opened the contacts 372, 373, 374 and 398. The moment the connection between the calling subscriber and the selecting impulse relay 365 is 110 completed in the manner described above the relay 365 is energized and a short circuit about the relay 375 is removed at 370 whilst the relay 371 is short circuited at 376. Thus the relay 375 is energized whilst the 115 relay 371 is de-energized. By the energization of relay 375 a circuit is prepared at 367 for the lifting magnet 377 of the wanted line selector. At 378 a circuit is prepared 120 for the change-over relay 379.

As the calling subscriber desires No. 134 he will cause three breaks of the circuit including the selecting impulse relay 365 in order to select the third tens group in the selected hundreds group. The relay 365 lets 125 its armature drop back three times in quick succession. The relays 371, 375 are kept energized during these oscillations and three impulses are sent through the lifting magnet 377 of the wanted line selector LWI 130

- which flow from the earth through 356, 380, 367, 381, 377, to the negative pole. The lifting magnet 377 lifts the brushes 382, 383 of the selector to the third contact level.
- 5 A short pause now ensues during which the calling subscriber sends no selecting impulses and during which the relay 365 keeps its armature steadily pulled up and closes the contact 376. The relay 371 now allows 10 its armature to drop back and a current flows from the negative pole through 373, 378, switch 384, which is closed upon the flowing of the first lifting impulse, 385, 379 to earth. The circuit changing relay 379 15 is thus energized and closes a locking circuit for itself which extends from the negative pole through 379, 386, 356, to earth. The relay 379 separates the selecting impulse wire 387 from the lifting magnet and 20 connects it to the turning magnet 389 which is arranged to move the brushes 383, 382 along the contact levels of the selector. To select the desired line in the third contact level the calling subscriber now causes four 25 interruptions of the selecting circuit which results in the selecting relay 365 allowing its armature to drop back four times. Four impulses then flow from the positive pole through 356, 380, 367, 390, 389 to the negative pole and the magnet 389 shifts the brushes 382, 383 onto the fourth set of contacts 391, 392 in the third contact level. At the end of the series of four interruptions of 30 the selecting circuit the relay 365 again steadily attracts its armature and causes the deenergization of the relay 371, whilst the relay 375 is kept energized. The earth is thus connected through 373, 378 to the test relay 393 of the selector. If the wanted 35 line is busy the potential on the test wire 3¹ of this line will be so low that the relay 393 will not be energized. The result of this will be that a busy signal current will flow from the busy signal machine 395, through 40 396, contact 397 that was closed when the brushes 383, 382 were moved by the magnet 389, contact 398, brush 340, wire 363, through the selecting circuit to the calling subscriber. On hearing the busy signal the 45 subscriber replaces his receiver on his instrument and thereby causes the switches used for the connection to return to their normal positions. These restoring operations will be described in subsequent paragraphs.
- If the wanted subscriber is free the test relay 393 is energized by a current that flows from the earth through 373, 378, 393, test wire 3¹ of the desired line and through this 50 wire to the relay of the wanted line that corresponds to the relay 16, Fig. 6, of the calling subscriber and to the negative pole. By the energization of the relay 393 a circuit is closed at contact 400 which extends from earth through 400, 372, 338, 401, 402,
- 403, motor magnet 404 of the wanted-line connector SV, to the negative pole. The motor magnet of the wanted-line connector now sets the set of brushes 405, 406, 407, a10, b10 in motion and this motion continues until the identifying relay 408 is energized by a current that flows through the identifying wire 409. This flow of current occurs as soon as the identifying brush 407 reaches the identifying wire 409. A circuit is then closed from the positive pole through 374, 383, 392, 409, 407 lower winding of the identifying relay 408, 410, 339, 411 to the negative pole. The relays 408 and 411 are thus energized simultaneously. The relay 408 opens the contact 403 and thus breaks the circuit of the motor magnet 404. The brushes of the wanted line connector are thus stopped on the line of the subscriber No. 134.
- When the relay 411 is energized its contact 412 closes a circuit which extends from the earth through 412, 413, relay 414 to the negative pole. The relay 414 closes a locking circuit for itself which may be traced from the negative pole through 414, 415, 356 to the earth. Relay 414 opens its contact 364 and thus breaks the circuit of the selecting relay 365 causing its armature to fall back and to short circuit the releasing relay 375 by its contact 370. After a brief interval the release relay lets its armature drop back and its armature contact 366 connects the interrupter 416 to the magnet 389. The magnet 389 now receives current impulses which flow from the earth through 416, 417, 366, 390, 389 to the positive pole and moves the brushes 382, 383 forward to the end of the third contact row where they drop and move back to their normal position.
- When the relay 411 is energized the locking circuit of relay 354 is opened at the contact 356¹. The armature of this relay closes the circuit of the motor magnet 322 through contact 326, 322, 348 and the motor magnet then moves the brushes of the selector connector LVI forward until it reaches its normal position, in which the contact 348 is opened and the circuit of the motor magnet 322 is broken. At the same time the locking circuit of the relays 379, 414 is broken by the opening of the contact 356 so that these relays allow their armatures to drop back.
- When the relay 408 opened the circuit of the motor magnet 404 at contact 403 it also closed the circuit of a relay 421 (earth 420, 422, 421, negative pole) by its contacts 420. The relay 421 connected itself to the wire 207 through contact 423, the wire 207 being connected to earth through the contact 269 of the relay 114, Fig. 7. The relay 421 thus closed a locking circuit for itself. At the same time it substitutes the connection be-

tween the wire 363 and the negative pole that is disrupted at the contact 364 of relay 414 by a connection through the contact 424, 425 to the negative pole. The connection between the negative pole and the wire 363 is required to maintain the energization of the release relay 114, Fig. 7.

The relay 421 substitutes a connection between the earth and the wire 3¹ through contact 426 and the brush 405 for the connection through the relay 393 and the contacts 378, 373 that is disrupted by the restoration of the selector LWI. As the test wire 3¹ is now directly connected to earth no test relays 393 that may hereafter be connected to this wire will be energized. The busy condition of the desired line is established the moment the test relay 393 of the wanted-line selector is energized due to the test relay 393 short-circuiting a part of its winding and thus lowering the test potential on the wire 3¹.

By closing its contacts 427, 428 the relay 421 establishes a ringing circuit and a ringing current then flows from the ringing machine 429 through the interrupter 430, relay 431, contact 432, 428, brush 610, wire 2¹ of the desired line to the desired subscriber, back through wire 1¹, a10, 427, 433 to the ringing machine 429. When the called subscriber responds by removing his receiver from its hook the ringing current flowing through the relay 431 is strengthened sufficiently to enable this relay to attract its armature and to close its contacts 435, 436. The contact 435 connects the wire 363 to earth and the contact 436 closes the circuit of the relay 437. This relay then connects itself to the wires 363, 363¹ by its contacts 438, 439, whilst the connection of the positive pole through 435 to the wire 363 results in the relay 440, Fig. 7, being energized by the following circuit: earth, 435, 363, 368, 208, 214, 240, 267, 252, 270, 298, 440, negative pole. The relay 440 opens its contacts 298, 297 and closes its contacts 296, 295 and by so doing switches itself into a new circuit that extends from the negative pole through 440, 296, 112, 277, a7, 1, 11, T, 12, 2, b7, 278, 113, 114 to earth. By the energization of the relay 440 the meter circuit is completed, this circuit extending from the negative pole through 229, 441, Z7, 4, meter 17 to earth. The connection established between the calling and called subscribers is thus registered. By the energization of the relay 437 the circuit of the ringing cut-off relay 451 is completed at contact 250 which circuit may be traced from earth through 450, 452, 451, to the negative pole. A new circuit is then closed for relay 437 which extends from earth through the right winding of 437, 439, 453, 428, 610, 2¹, called station, wire 1¹, a10, 427, 434, 438 to the negative pole. The relay 427 is slow-acting and therefore a possible

opening of the contact 436 by the disconnection of the relay 431 from the called line at the contacts 432, 433 will not result in the immediate falling back of the armature 437 and this is kept attracted until the contacts 434, 453 are properly closed and until the described circuit through the windings of the relay 437 and the station of the called subscriber is established. The opening of the contacts 433, 432 which is caused by the energization of the relay 451 results in the de-energization of the relay 431 and in the disconnection of the ringing machine 429 from the called line. The transmitter of the called station is now supplied with current through the windings of the relay 437, whilst the calling subscriber receives current through the windings of the relays 114 and 440. The calling and called lines are now connected to each other through the following talking current circuit: calling station T, 11, 1, a7, 277, 112, condenser 470, 269, 251, 266, 241, 215, 209, 362, 363, 434, 427, a10, limb 1¹ of the wanted line No. 134, station No. 134, return limb 2¹, b10, 428, 453, 363¹, 368, 208, 214, 240, 267, 252, 270, 297, 471, 113, 278, b7, 2, 12, calling station T.

When the calling subscriber T replaces his receiver at the end of the conversation he interrupts the current flowing through the relays 114, 440, Fig. 7 and this causes the connection between the wire 120 or 268 and earth to be broken by contact 269. Since the relays 279, 16, 265, 359, 301, 255, 421, 451 receive their current from earth through the wire 120 or 268 the disruption of this connection by the de-energization of the relay 114 results in the de-energization of all the said relays. By the retraction of the armature of 201 the primary trunk finder EVII is caused to return to its position because of the completion of the circuit of the motor magnet 148 at 145. The brushes of the other switches remain in the positions in which they happen to be, but the talking circuit is opened in these switches by the relays just mentioned.

The breaking down of the talking connection may also be brought about by the called subscriber replacing his receiver. This could be accomplished by supplying the current from earth through contact 269 to the wires 120, 268 through a resistance and by short-circuiting the relays in the various switches by causing the relay 437 to connect the negative pole to the wires 120, 268 when it is de-energized by the called subscriber replacing his receiver and opening his line loop.

The means by which the secondary trunk finders are enabled to identify the trunk that is connected to the correct calling line amongst a number of lines which are also in the calling condition have already been briefly described, but a more detailed de-

scription will now be given with the aid of Fig. 13.

This figure represents the primary and secondary trunk finders of two different hundred groups. The sets of group selectors and group selector connectors belonging to these hundred groups are also shewn. The various switches of Fig. 13 are marked with the same reference characters as the corresponding switches of Figs. 7, 8, 9, 11 and 12. Only the circuits or current paths of these switches that form parts of the identifying means by which the secondary trunk finders are enabled to always identify and stop upon the correct trunk Z_1 , Z_2 — z_1 , z_2 are shown. In order that the task which the identifying circuits have to fulfil may be perfectly understood it will now be restated. Suppose a subscriber A that wishes to connect his line to the another line in the first hundred makes a call. He will first be connected in the manner previously described to a secondary trunk, e. g. Z_1 , which has been seized by say GVI . The calling subscriber A now selects the selecting wires leading to the desired first hundred group by the aid of the group selector GW_1 and starts the idle primary trunk finders EV_1 , EV_2 , EV_3 of the first hundred group as previously described. One of these finders, e. g. EV_2 , will now seize a primary trunk E_1^1 and the secondary trunk finder $ZVII$ belonging thereto will then be started. This secondary trunk finder must stop its brushes on the contacts that are connected to the secondary trunk Z_1 to which the calling subscriber A and the group selector connector GVI are connected. It may happen that whilst these operations are progressing another subscriber B makes a call who wishes to be connected to a subscriber in the second hundred group and who has been connected to a secondary trunk Z_2 which is seized by the group selector connector $GVII$. The calling subscriber B moves the brushes of the group selector GW_2 onto the selecting wire leading to the second hundred group and thus causes the primary trunk finders EV_1 , EV_2 , EV_3 in this group to start hunting. One of these finders e. g. EV_3 , will seize an idle trunk E_2^1 and the secondary trunk finder $ZVIII$ belonging this trunk will be started. The secondary trunk finder $ZVII$ started by the subscriber A (who desires the first hundred group) and the secondary trunk finder $ZVIII$ started by the calling subscriber B (who desires the second hundred group) now move simultaneously over the contacts of the secondary trunks Z_1 , Z_2 . If the secondary trunk finder $ZVIII$ were to stop on the trunk Z_1 the calling subscriber A, who wishes to be connected to the first hundred group would be connected to the second hundred group,

and if the secondary trunk finder $ZVII$ were to stop on the trunk Z_2 the calling subscriber B, who wishes to be connected to the second hundred group, would be connected to the first hundred group. To prevent wrong connections of this kind, the identifying circuits are provided which are illustrated in Fig. 13, and which always cause the secondary trunk finders to identify or distinguish the proper calling line or the secondary trunk connected to the proper calling line. It will be seen that from each group selector a separate wire (i. e. a wire connected to the particular group selector only and not to a plurality of group selectors) leads to each group of primary trunk finders. Thus a separate identifying wire 132^1 leads from the group selector GW_1 to the primary trunk finders EV_1 , EV_2 , EV_3 of the first hundred group and a separate identifying wire 132 leads from the group selector GW_2 to the primary trunk finders of the first hundred group. In a similar manner a separate identifying wire 133^1 leads from the group selector GW_1 to the second hundred group EV_1 , EV_2 , EV_3 and a separate wire 133 leads from the group selector GW_2 to this group.

In the same way separate identifying wires 532^1 , 532 extend from the group selectors gw_1 , gw_2 to the first hundred group and a separate wire from each group selector gw_1 , gw_2 to the second hundred group. Each group selector connector also has separate identifying wires leading from its contacts to the contacts of the secondary trunk finders. Thus the group selector connector GVI has a separate set of identifying wires 253^1 , 254^1 , 653^1 and the group selector connector $GVII$ has a separate set of identifying wires 253 , 254 , 653 . The upper brushes e^1 , e^2 , e^3 of the secondary trunk finders ZVI , $ZVII$, $ZVIII$ wipe over the contacts of the identifying wires of the group selector connector GVI only, and on tracing the connections of the brushes e^1 , e^2 , e^3 through the wires f^1 , f^2 , f^3 and through the connections that cooperate with these wires through the brushes, 210 , 210^1 , 210^2 and the wires 132^1 , 133^1 and through the brushes 710^1 , 710^2 , 710^3 and the wires 533^1 , 532^1 , it will be evident that a current through a brush e^1 , e^2 or e^3 can only flow from the positive pole connected to the brush of the group selector connector GVI to the negative pole connected to the brush 126^1 of the group selector GW_1 , which latter brush wipes over the identifying wires 132^1 , 133^1 . In a similar manner a circuit through the lower brushes k^1 , k^2 , k^3 can only be closed by way of the brushes of the group selector connector $GVII$ and of the corresponding group selector GW_2 . Therefore if a group selector GW_2 is set onto the wire 132^1 it will only be possible for a cir-

cuit to be closed through a brush e^1 , e^2 or e^3 that comes into contact with a wire 253¹, 254¹, 653¹ which is connected by the corresponding group selector connector GVI to the positive pole. But as only one of these wires can be connected to the positive pole at a time the brush of the particular secondary trunk finder, e. g. the brush e^2 will only be able to close a circuit when it reaches the wire, e. g. 253¹ onto which the group selector connector GVI is set. If the secondary trunk finder ZVI is used for the talking connection the primary trunk finder EVII will have set its brushes onto the primary 15 trunk E¹, and the moment the brush e^2 reaches the wire 253¹ a current will flow from the positive pole connected to the brush of GVI through 253¹, e^2 , f^2 , 210 lower winding of 255, 222, 225, 132¹, brush 126¹ of the 20 group selector GWI to the negative pole. The relay 255 is thus energized and stops the brushes of the secondary trunk finder ZVII in the manner described in connection with Fig. 9. If the brushes of the secondary 25 trunk finder were to contact with a secondary trunk that is connected to a group selector connector GVII no circuit could be closed through the brush e^2 or k^2 of the secondary trunk finder ZVII because the brush 30 126 of the group selector GWII connects the negative pole through a brush 715¹, 716¹ or 717¹ only to a brush k^1 or k^3 of one of the other secondary trunk finders ZVI or ZVIII. The connecting of two primary 35 trunk finders to one and the same secondary trunk finder, e. g. ZVII, is prevented by the testing devices of the primary trunk finders previously described.

The stopping of a secondary trunk finder 40 that is started as the result of a call from a subscriber A upon a secondary trunk which is connected to a calling subscriber B is only possible if the two subscribers A and B select the same group. But in a case like this 45 the identification of the subscribers by the secondary trunk finders is unnecessary. The reason why no identification takes place (nor need take place) in a case like this is that the identifying wires of the same hundred 50 group, e. g. 132¹, 132, may both be connected to the negative pole at the same time. The two brushes e and k of the travelling secondary trunk finders will then be simultaneously connected to the negative pole and as 55 soon as the brush e or k contacts with a wire connected to the positive pole, e. g. 253 or 253¹, the upper or lower winding of the particular identifying relay, e. g. 255, will be energized and the particular secondary 60 trunk finder ZVIII will be stopped. The simultaneous connection of the brushes e and k of a secondary trunk finder is, as has already been said, only possible when the group selectors GWI, GWII of a calling 65 group are caused to select the same hundred group and if, in a case like this, the secondary trunk finder started by a calling subscriber A stops on a trunk that is connected to the other calling subscriber B, or on the trunk that is connected to A, it will make no difference since both subscribers A and B wish to be extended to the same group. The identifying means used in the calling-line connectors and in the wanted-line connectors to enable these switches to identify the correct calling or called line are based on the same inventive idea as the identifying means used in the group selectors and secondary trunk finders, so that they will be understood without any further explanations by referring to the drawings.

In the preceding paragraphs the secondary trunk finders, e. g. 15, 16, 17, Fig. 1 have been described as a revertively-acting finders. Instead of these finders forwardly 85 acting finders could be used whose movable contacts are connected to the trunks 31, 32, 33 and whose fixed contacts are multiply connected to the trunks 40, 41, 42.

Fig. 14 illustrates how the number of 90 trunk finders may be reduced by omitting the secondary trunk finders. In this figure the quick-acting finders R, the calling line connectors V, the group selectors GW etc. are marked with same signs of reference as 95 in Figs. 6 to 12. The front fixed contacts of the trunk finders EV, Ev are directly connected to the trunks Z¹, Z² instead of to secondary trunk finders.

The operation of this system is as follows: On a calling subscriber's receiver being removed a quick-acting finder, e. g. RI moves its brushes onto the calling line, e. g. 2, as explained in Figs. 6 and 7. The calling subscriber then causes a group selector, e. g. 100 GW, to select the wanted group, e. g. the first group as described in Fig. 6, whereupon current impulses flow from the positive pole through the interrupter 139¹, brush 125¹, wire 129¹, motor magnets 147¹ of the idle 105 trunk finders EVI, EVII etc. of the first group to the negative pole. If the group selector connector GVI has its brushes resting on the trunk Z1 the identifying relay 255¹ of the finder EVI will be energized as 110 soon as the brush 211¹ reaches the identifying wire 217 of the trunk Z1. The energizing current will flow from the negative pole through 126^{1y}, 132¹, 223¹ upper winding of 255¹, 211¹, 217, brush 100¹ of the group 115 selector connector GVI to the positive pole. The identifying relay 255¹ closes its contacts 300, 301 and by the closure of 301 relay 302 is energized which de-energizes the motor magnet 147¹ and thus stops the finder. The closure 120 of contact 300 results in the starting of further group selector connectors or wanted-line selector connectors in the manner represented in Figs. 9 and 10 so as to connect the trunk SVI to another group selector or wanted- 125

line selector. When the relay 302 is energized the talking wires of the trunk Z1 are extended to the trunk SVI. By this means the calling subscriber's line 1 is also extended to the next group selector or to the wanted-line selector. In the meantime the connector VI belonging to the trunk Z1 will have moved its brushes into contact with the calling line 2 in the manner described in Fig. 6 so that the calling subscriber 2 will now be connected through the connector VI and the trunk finder EVI to the trunk SVI leading to the wanted group of lines. Many details and operations are omitted in Fig. 14 because the switches R, VS, V, EV and GW operate similarly to the corresponding switches of Figs. 6 and 7.

A drawback is involved in the system shewn in Fig. 14 which will now be explained: Suppose a group selector connector GVI has set its brushes onto a trunk Z1. The trunk finder EVI or E_{v1} corresponding to this trunk will then have to be idle in the group selected by the calling subscriber or else the calling subscriber will not be extended to a trunk SV in the desired group. The reason of this is that there are no further connecting paths through the fixed contact sets of the other finders EVII, EVIII or E_{v2} , E_{v3} leading to the trunk Z1. The finder EVI thus accords the only possible connection between the selected group and the trunk Z1. But it may happen that at the moment the subscriber 2, who is connected through a quick-acting finder R and a connector-finder to a trunk Z1, selects the first group, the finder EVI that accords the only possible connection between the trunk Z1 and wanted group is being used for a connection from some other calling group. The calling subscriber in the first group would then obtain no connection even if other trunks Z2 or Z3 are still idle. This drawback can be removed by connecting each of the trunks Z1, Z2, Z3 to several finders EVI, EVII, EVIII as shown in Fig. 15 instead of connecting each to one finder only.

It will be seen from Fig. 15 that each of the trunks, e. g. Z2, Z3 are connected to the fixed contacts of two finders EVI, EVII of the first group and to two finders, E_{v1} , E_{v2} of the second group. Thus each of the trunks Z2, Z3 may be extended by several trunk finders in each group to a free trunk SVI, SVII or sv_1 , sv_2 . If the connecting of the trunks Z1, Z2, etc., z_1 , z_2 , etc., to several trunk finders in each group is followed to its ultimate consequences each trunk finder EVI, EVII, etc., E_{v1} , E_{v2} , etc., would be provided with as many sets of bank contacts as the total number of trunks E^1_1 , E^1_2 — E^2_1 , E^2_2 and these trunks would be simply connected in multiple to the bank contacts of the trunk finders. On each trunk finder

a contact segment would be arranged for each identifying wire from the group selectors GWI, GWII, gw_1 , gw_2 so that the number of contact segments in each set of segments would be equal to the number of group selectors in the calling group to which the set of segments corresponds as indicated in Fig. 16. In this figure only the identifying wires and the group selectors, group selector connectors and trunk finders of two subscribers' groups are shown. A representation of the other switching paraphernalia is unnecessary because this can be inserted with the aid of the foregoing description and the Fig. 16 by anyone skilled in the art.

Another method by which the poor trunking efficiency of Fig. 14 can be removed is shewn in Fig. 17. In this figure the switching devices of two subscribers' groups are represented. The subscriber T belongs to one group and the subscriber T1 to another. When a subscriber calls he is connected by a finder RI or RII to an idle group selector GWI or GWII. The finders RI, RII are preferably made quick-acting. For the sake of simpler explanation they are shewn as ordinary finders in Fig. 17. When a calling subscriber T is connected to a group selector, e. g. GWI, he sets the brushes of this selector onto the desired group, e. g. the first hundred group. After the brushes of the group selector have reached the desired group a set of trunk finders EVI, EVII, EVIII in this group is started. Each of these finders has only one trunk leading to the calling group. When one of the finders has seized a free trunk, e. g. Z1, the connector VI is caused to move its brushes on to the calling line which is marked by the identifying wire connected to the quick-acting finder which took up the call. The moment the connector VI reaches the line of the calling subscriber T this line is extended through the connector VI and the particular trunk finder EVI to the trunk VLI. This leads in the manner shewn in Figs. 6 to 12 to a final selector, a wanted line connector, or to another group selector as shewn in Figs. 4, 5.

The detailed group selecting operations in the system shewn in Fig. 17 are as follows:—When the calling subscriber T raises his receiver a current flows from the positive pole through the common relay 1, 2, 7, T, 9, 6, 11 to the negative pole. The relay 1 closes contact 12 and completes the circuits of the motor magnets 13 and 20 of the finders RI, RII and these move their brushes over the subscribers' contacts. As soon as the brush 21 of a finder, e. g. RI, reaches the earthed contact 6 of the calling subscriber a current flows from the negative pole through contact 17 of the relay 22, upper winding of this relay, brush 21, 6, contact 130

9 of relay 50, T, 7, 2, relay 1 to the positive pole. The relay 22 of the finder RI opens the circuit through its upper winding and at its contact 18 it closes another circuit extending from the positive pole through contact 23 of the relay 51, lower winding of relay 22, brush of RI, 3, relay 50 to the negative pole. The circuit of the motor magnet 13 is opened at contact 14 so that the brushes 10 of the finder RI stop on the bank contacts of the calling line. At the same time the relay 50 is energized and the subscriber's station T is extended through 8, 4, 16 and through 10, 5, 15 to the selecting impulse relay 27 16 of the group selector GWI. Another simultaneous function is the closure of the contact 19 of the relay 22 of RI by which the negative pole is connected to identifying wire e1 of the subscriber T and a stopping 20 circuit is prepared for a subsequently operated connector.

The selecting relay 27 is energized by a current which flows through the calling subscriber's loop. By closing its contact 28 it energizes the release relay 35 in a circuit extending from the negative pole through 28, 35 to earth. The relay 35 closes its contacts 39, 40 and opens the contact 41 of the release circuit. By closing contact 39 the relay 35 30 completes an auxiliary locking circuit extending from the negative pole through resistance 42, 39, 35 to earth. This auxiliary locking circuit keeps the releasing relay energized until the relay 27 is steadily de-energized when the release relay will be steadily short circuited. The closure of the contact 40 results in the energization of the relay 34 by a current flowing from the negative pole through 43, 40, 34 to earth. The 40 change-over relay 34 opens the contacts 36, 37, 38 and thus disconnects the negative pole from the brushes of the group selector. If the relay 27 is kept steadily energized the change-over relay will be de-energized by 45 a short-circuit from earth through 30 which will take all the current from the negative pole through 43 and 30. When the calling subscriber sends in his selecting impulses by causing openings of his loop the armature 50 of the relay 27 falls back at each such opening. If the calling subscriber wants the first group he will cause one opening of his loop so that the armature of 27 falls back once and is then pulled up again. This causes a 55 current impulse to flow from the negative pole through 43, 31, motor magnet 32 to the positive pole which steps the brushes of the group selector forward one step so that they engage with the selecting wire L1. The relay 34 which was energized by the opening of the contact 30 when the armature of 27 fell back lets its armature drop back again when the relay 27 is excited continually and then connects the negative pole to the three 60 brushes of the group selector through 36, 37,

38. This energizes the motor magnets of the trunk finders EVI, EVII, EVIII of the desired group and starts them. Since these finders are all similarly arranged it is only necessary to show the circuits of one of them, e. g. EVI. When the group selector brushes 81, 82, 83 have been moved on to the desired group as described the motor magnet of this trunk finder is energized by a current flowing from the negative pole through 36, 81, starting wire 80, 63, 65 to the positive pole. The motor magnets of the other finders EVII, EVIII will be simultaneously energized in a similar manner. The group distinguishing contacts 85, 86, 87 of the finders are connected to the negative pole through the wire 88 and through brush 82 and contact 37. Hence the test relays 62 of each finder EVI, EVII, EVIII will each test a trunk Z1, Z2 and Z3 respectively when the contacts 85, 86 and 87 are reached by the brushes 89, 91 and 91 respectively, but no testing of the trunks leading to other non-calling groups will take place. It will be assumed that the trunks Z2, Z3 are busy and that the trunk Z1 is free. This being so a current will flow, when the brush 89 reaches the contact 85, from the negative pole through 37, 82, 88, 85, 89, 61, test relay 62, brush 92, wire 98 of the trunk Z1, 100, relay 101 to the positive pole. The test relay 62 is energized and short-circuits a part of its winding, whilst opening its back contact 61 and closing a new energizing circuit for itself through a front contact. This causes a strengthening of the current that flows through the relay 101 so that this relay pulls up its armature and closes the circuit of the motor magnet 102 of the connector VI. The brushes of the connector VI now travel over the contact sets of the subscribers' lines in the calling subscribers' group until the identifying brush e3, which corresponds to the identifying wire e1 of the group selector GWI or of the finder RI, reaches the identifying wire e1. The identifying relay er will then be energized by a current which flows from the positive pole through relay 24, contact 19 of the relay 22, resistance 103, lower brush of RI, e1, e3, upper winding er, wire 104, Z1, brush 97, brush 105, wire 108, brush 83 of GWI, 38 to the negative pole. If the calling subscriber had been connected by a different quick-acting finder RII to a different group selector GWII the identifying relay er would have been energized by a current that flowed through the identifying wire e2 of the second finder RII and through e4, 105, 96, 106, 108 and brush 109 of the group selector GWII.

When the relay er is energized the circuit of the relay 101 and of the motor magnet 102 is broken. Simultaneously the contact 110 of relay er is closed and a relay 111 is thus 120

energized which closes its contacts 112, 113, 114 and extends the line *a*, *b*, of the calling subscriber to the trunk Z1. A current then flows from earth through the release relay 5 116, 113, *b*, *T*, *a*, 112, 117, 118, 94, back contact 119 of the relay 72 of the finder EVI, resistance 115 to the negative pole.

The energization of the identifying relay 10 *er* was accompanied by the energization of the relay 24 of the finder RI. The latter relay opens its contact 23 and breaks the circuit including the lower winding of relay 22 and the relay 50. The relay 24 short-circuits itself by its contact 24 so that it slowly 15 lets its armature drop back. In the meantime the relay 116 will have attracted its armature and completed a new circuit for relay 50 (through 120, 121, bottom brush of VI, 3, 50 negative pole) which is only dependent on the release relay 116.

By the de-energization of 22 the connection between the calling line and the relay 27 is disrupted. The relay 27 is thus de-energized and the contact 29 steadily closed so 25 that the release relay of the group selector GWI is deenergized and the circuit of the release magnet 33 is closed at 41. The brushes of the group selector GWI are then restored to their normal position.

30 During the operations that took place after the finding of the trunk Z1 a second group selector connector, which will have been started by the closure of contact 68 of the relay 79, will have been caused, by similar means to those shewn in Fig. 10, to make connection which the trunk VLI which is put into the calling condition by the closure of contact 69. The moment this trunk is reached by the second group selector connector or wanted-line selector connector (not shewn) a relay 72 is energized and this connects itself to the brush 95 and the earthed wire 121 by closing its contact 74. On the energization of relay 72 the calling line *a*, *b* 45 is extended through the contacts 76, 78 to the trunk VLI. The remaining operations in establishing the connection with the wanted-line are similar to those of Figs. 9 and 10 which have already been described.

50 It will be seen that if the number of subscribers in a group is large an appreciable time might elapse before a subscriber, whose call is passed on through a quick-acting finder R to a group selector, is ultimately 55 extended through a connector V to the desired group. If there are 100 subscribers *T* in a group it may happen that the brushes of the connector used will have to pass over 99 sets of contacts before reaching the calling line. In order to enable the calling subscriber *T* to send in the next series of selecting impulses, after the operation of the first 60 group selector, as soon as possible it is desirable that the calling line be extended to the next numerical switch (group selector,

wanted line selector) as rapidly as possible. This can be accomplished in different ways.

First, the connectors may be made quick-acting like the quick-acting finders of Fig. 6. Secondly, connectors may be used having 70 a number of bank contact levels instead of one level only each level containing a sub-group of the whole group of lines. The brushes of the connectors will then execute a few steps to reach the sub-group or contact level of a calling line and will then execute a few more steps to reach the particular calling in the contact level. Thirdly, the circuits may be arranged so that when a group selector has operated and a free trunk 80 has been found by a trunk finder EV the next series of impulses are sent through the brushes of the group selector to the next group selector or wanted-line selector that is connected to the particular trunk VL, so 85 that the calling subscriber need not wait till a connector V has reached his line before sending the next series of selecting impulses. A fourth method is to provide each sub-

scriber's line with a forwardly-acting connector, which is started when an idle trunk Z is reached by a trunk finder EV and is then also caused to move its brushes onto the idle trunk Z found by the trunk finder EV. This fourth method is illustrated in Fig. 18 in 95 which the switching devices of one group are represented. The trunk finders EV, the group selectors GW and the quick-acting finders R are similar to the corresponding switches of Fig. 17. But the connectors differ in that one connector V is provided for each subscriber's line whose brushes are connected to the subscriber's line. These brushes move over bank contact sets that are connected in multiple and to the trunks Z1, 100 Z2 etc. of the subscriber's group as indicated. The trunks Z1, Z2 etc. lead to fixed contacts of different groups of trunk finders Ev, Ev in the manner shewn in Fig. 17.

When a subscriber *T* of Fig. 18 calls, a 110 common relay 1 is energized and this closes the circuits of motor magnets 2 of quick-acting finders RI, RII as in Fig. 17. The brushes of the quick-acting finders are then moved over the bank 115 contacts of the subscribers' lines until a brush set of one of the finders, for example RI, reaches the contact set of the calling subscriber *T*. Relays 3 and 4 are then energized and the calling subscriber is connected as in 120 Fig. 17 to a group selector GWI. The calling subscriber now sends selecting impulses through the selecting relay 5 and thus moves the brushes of the group selector onto the selecting line, e. g. L1, that leads to the 125 desired group. The idle trunk finders in this group, e. g. EVI, EVII are then started hunting for an idle trunk. Up to this point the operations of Fig. 18 are similar to those of Fig. 17 as previously described. When a 130

trunk finder, e. g. EVI, has found a free trunk Z1 its test relay 8 attracts its armature and closes a contact 10 which is absent in Fig. 7. A current flows through this contact 5 from the negative pole through 10, 11, 12, 13, 14, relay 15, 23 to the positive pole. The relay 15 of the quick-acting finder is thus energized and closes a circuit which extends from the positive pole through 18, 17, 10 19, 20, 21, 25, motor magnet 22 to the negative pole. The brushes of the connector VI of the calling subscriber are now moved and they continue to travel until a circuit is closed through the identifying wire e1 that 15 corresponds to the quick-acting finder RI. This circuit extends from the positive pole at the group selector, through 26, 27, e3, 28, 29, 30, 31, lower winder of relay 32, e1, 33, 35, relay 34 to the negative pole. 20 If the other quick-acting finder RII had seized the calling line T another stopping circuit instead of the circuit just described would have been closed, and this circuit would have included the identifying wire 25 e2, that corresponds to the quick-acting finder RII, and the wire e4 and the upper winding of the relay 32.

The circuit described in the second last paragraph energizes the relay 34 and by 30 opening its contact 19 it breaks the circuit of the motor magnet 22 so that the brushes of VI stop on the contacts of the trunk Z1. During the motion of the brushes of VI the connection between the battery B1 and the 35 brushes 39, 40 or 35, 36 is disrupted at the contacts 37, 38 of relay 15 and during the interval of disruption the relay 5 is kept energized by a current through the resistance 41 in order to prevent the release of the 40 group selector GWI which would result from the de-energization of 5.

But the moment the relay 34 is energized in the manner described by a current flowing through the identifying wire, the circuit of the relay 15 is opened at 23. The relay 3 is simultaneously de-energized by the opening of 42 and by the energization of the relay 32 the relay 43 is energized through 44 and this relay closes its contacts 25, 46, 50, 47 and opens contact 48. By the closure of contacts 46, 47 a circuit is completed from earth through the relay 49, 47, 36, T, 35¹, 46, 55, 51, 52, resistance 53 to the negative pole. The relay 49 connects earth or the positive pole to the wire 56 and the energization of the relay 4 is thus maintained by a current flowing from the negative pole through 55, 56, 54 to earth. In order that the opening of the contact 60, which happens almost immediately the relay 34 is energized, may not be followed by the immediate de-energization of the relay 4, a short-circuiting contact 21¹ is provided on the relay 34 which causes this relay to fall back sluggishly and also causes the positive pole to remain connected

through 61, 62 to the wire 63 and the relay 4 until the relay 49 has connected the positive pole through 54. In order to prevent the sure energization of the relay 32 being endangered by the quick opening of the contact 35 this relay may also be kept shunted by connection to the negative pole as long as the slowly-retracting relay keeps its armature attracted. 70

The de-energization of the relays 3 and 34 75 is followed by the deenergization of relay 5 and the restoration of the group selector GWI. By the energization of the relay 43 the calling subscriber's line is extended to the trunk VII. At the end of the conversation 80 the connection is broken down by the de-energization of the relay 49.

Fig. 19 illustrates an application of the invention to an exchange in which no group 85 selectors are used. RI, RII represent quick-acting finders LWI, LWII are wanted-line 90 selectors, Vv1, Vv2, Vv3 are calling-line connectors and Vs1, Vs2, Vs3 are wanted-line 95 connectors.

When a subscriber T calls a common relay 1 is energized in the same manner as in previous figures and this relay closes the circuits of motor magnets 2, 2¹ of the finders RI, RII. The moment the brushes of a finder, e. g. RI, reach the calling line the subscriber's line is extended as in the previous systems to a numerical switch, the numerical switch in Fig. 19 being a wanted-line selector LWI. The wanted-line selector is then set by selecting impulses from the calling 100 subscriber T onto the wanted line, say the line of the subscriber T1. If this line is free the contacts 3, 4, 5 in the wanted-line selector are closed. By the closure of contact 3 the negative pole of the battery is connected to the identifying wire e3 whilst the closure of contact 4 connects the negative pole through a resistance 6 to a test wire 7. By the closure of contact 5 the circuits of the motor magnets 8, 9, 10 of the connectors 110 Vs1, Vs2, Vs3 are completed and these magnets cause the brushes of the connectors to travel over the bank contacts of the subscribers' lines. As soon as the brushes of a connector, e. g. Vs2, reach the line selected by the selector LWI the test relay 16 of the connector is energized by a current that flows from the positive pole through the relay 16, brush 11, wire 7, brush 12, 4, resistance 6 to the negative pole. The relay 16 closes its 115 contacts 14, 15, 16, 17 and opens its contact 18. By the closure of the contact 16 the potential on the wire 7 is reduced in a known manner, so that other connectors Vs are no longer able to seize the line of the wanted 120 subscriber T1. By the opening of contact 18 the connector magnet 9 is de-energized so that the brushes of the connector Vs2 stop on the line of the subscriber T1. The closure 125 of the contact 17 causes the energization of 130

the motor magnet 19 of the connector $Vv2$ so that the brushes of this connector are made to travel over the bank contacts of the subscribers. Since the contacts 14, 15 are closed by the relay 16 and the identifying wire $e3$ is connected by 3 to the negative pole, the upper winding of the identifying relay er^2 will be energized the moment the brush 20 reaches the identifying wire $e1$ that 10 is connected to the positive pole by contact 21 and that corresponds to the finder RI or the wanted-line selector LWI . The motor magnet 19 will thus be de-energized and the calling line will be connected to the desired 15 line T through the connectors $Vv2$, $Vs2$.

The circuits could also be arranged so that at the moment the wanted-line selector is set onto the wanted line $T1$ a free connector Vv is caused to connect to the calling 20 line, whereupon the connector Vs belonging to the connector Vv is caused to find the called line by means of identifying wires.

The system will preferably be arranged (as in Figs. 17 and 18) so that when a connection between a calling and called subscriber T and $T1$ is established the switches R , LW revert to common use.

The connectors Vv may also be made to act as forwardly acting finders instead of 30 revertively-acting finders as shown in Fig. 19. Each subscriber's line would then have its own connector.

In Figs. 1 to 13 the primary trunk finders, i. e. the switches 18, 19, 20 of Fig. 1 for example are shewn as revertively-acting finders. They may however, be made to act as forwardly-acting finders, if a different grouping and arrangement of the trunks and of the system is employed. This system 40 is shewn in Figs. 20^a and 20^b. In these figures three subscribers' groups, CS^1_1 , CS^2_1 , CS^3_1 — CS^1_{II} , CS^2_{II} , CS^3_{II} — CS^1_{III} , CS^2_{III} , CS^3_{III} are illustrated. The first group has a set of primary trunk finders PF^1_1 , PF^2_1 , 45 PF^3_1 , a set of secondary trunk finders SF^1_1 , SF^2_1 , SF^3_1 , a set of connectors F^1_1 , F^2_1 , F^3_1 , a set of group selectors GS , a set of group selector connectors SC and a set of wanted line selectors LW^1_1 , LW^2_1 , LW^3_1 . The other 50 groups of subscribers are provided with sets of switches that correspond to those of the first group. The upper bank contacts of the primary trunk finders PF are connected so that each contact set of each finder leads 55 to a wanted line selector in a different group. The lower bank contacts of the primary trunk finders PF of a group all lead to contacts of group selectors of the same (calling) subscribers' group. When 60 a subscriber, say CS^1_1 , calls, he is first connected to a group selector GS^1_1 and he then sets this selector onto a selecting line, e. g. 8, which leads to the desired group. A circuit is then closed through the wire 5 which 65 includes the motor magnets d^1 , d^2 , etc., of

the primary trunk finders PF^1_1 , PF^2_1 , PF^3_1 of the wanted group so that these finders are all started. As soon as the identifying brush, e. g. b^1 , of a primary trunk finder PF^1_1 reaches the wire 8, which is connected 70 through 6, 1, 2 to the negative pole, a relay h^1 that corresponds to the motor magnet d^1 , will be energized provided that the test brush t^1 simultaneously contacts with a free line 510 leading to a final selector LW^1_{II} 75 of the wanted group. At the same time an identifying wire 18 is simultaneously connected to the negative pole and a stopping circuit is thus prepared for a secondary trunk finder SF . A relay 6 in the group 80 selector GS^1_1 is energized simultaneously with the relay h^1 and this causes the energization of a motor magnet 7 of a secondary trunk finder SF^1_1 through a contact 9 and brush 11. The brushes of the secondary 85 trunk finder are now moved until the relay 26 is energized by a current from the positive pole through 15, right winding of 26, wire 18, winding 19, contact 514 to the negative pole. The calling subscriber is 90 now connected through a finder F^1_1 and through the secondary trunk finder SF^1_1 and the primary trunk finder PF^1_1 to a final selector in the desired group. The other operations in the establishing of a 95 connection are similar to those described in the preceding pages.

It will of course, be understood that one or more common batteries may be employed in any exchange arranged according to this 100 invention.

It will be further mentioned that modified types of switches may be used instead of the quick-acting finders shown in Figure 6. Thus instead of driving all the sets of 105 brushes of a quick-acting finder by a single driving device, the quick-acting finder may be split up into a number of small switches, each having one set of brushes and an individual driving mechanism. Upon a subscriber, making a call, the set of brushes that travels over the sets of bank contacts amongst which the calling subscriber's bank contacts are contained, will be set in motion and will stop on the said bank contacts, 110 whereupon the calling line will be extended to a connection finder, group selector or wanted line selector as the case may be. Of course, the circuits will be arranged similarly to those previously described so as 115 to prevent several calling subscribers being simultaneously extended to the same trunk.

Each quick-acting finder of Fig. 6 could also be replaced by a series of relays containing one relay for each calling line. Thus if two quick-acting switches are to be provided as in Fig. 6, and if there are 100 calling lines there would be two series of 120 100 relays each. The circuits of these series 125 130

of relays are so arranged that when a subscriber calls, the relay which is associated with his line in the series of relays representing the idle quick-acting switch will be energized and will extend his line to a free trunk.

I claim:—

1. In a telephone system, a switch with groups of bank contacts, telephone lines connected to the groups of bank contacts, sets of brushes on the switch adapted to be shifted onto the said groups of bank contacts in succession, a link circuit coordinated to the said brushes, a group testing relay for testing each group of lines onto which the sets of brushes are set, and individual test relays for testing a line through one set of brushes and extending a free line to the said circuit.

2. In a telephone system, telephone lines, stationary contacts connected to the said telephone lines, a plurality of simultaneously moved brushes adapted to cooperate with the said stationary contacts, a link circuit, means for extending a said line through a said brush to the link circuit, and a switch for also automatically extending the said line to the said link circuit.

3. In a telephone system, talking circuits, a switch with groups of bank contacts connected to the said talking circuits, means for establishing a busy condition on each said circuit when it is taken into use, a set of brushes cooperating with the said bank contacts, a group testing means for testing a group of said talking circuits, and a testing means for testing each said talking circuit individually.

4. In a telephone system, telephone lines, means for testing said lines in groups, means for testing the lines of a group individually, a link circuit, means for connecting a free line to the link circuit with the aid of the said testing means, switches, and means for controlling the said switches by currents flowing through a telephone line and the said link circuit.

5. In a telephone system, telephone lines, a link circuit, a finder with sets of simultaneously hunting brushes, a test relay associated with each said set of brushes, means for connecting a telephone line through a set of brushes and a test relay to the link circuit, and another finder for connecting the telephone line to the said link circuit.

6. In a telephone system, telephone lines, calling means associated with the said lines, line finders with bank contacts connected to the said lines, a finder starting relay common to the said telephone lines, an energizing circuit extending through the finder starting relay and directly through any said telephone line, means for setting a said finder onto a line when it calls, and means

for opening the energizing circuit when the finder is set onto the said calling line.

7. In a telephone system, telephone lines, calling means associated with the said lines, line finders with bank contacts connected to the said lines, a finder starting relay common to the said telephone lines, an energizing circuit extending through the finder starting relay and directly through any said telephone line, means for setting a said finder onto a line when it calls, and a relay associated with each line for opening the said energizing circuit when the finder is set onto the said calling line.

8. In a telephone system, subscribers' stations, numerical impulse transmitters associated with the said stations, outgoing conversational circuits, intermediate conversational link circuits between the subscribers' stations and the said outgoing conversational circuits, selectors with circuit selecting contacts that always move in the same plane and are affected only in response to said impulse transmitters, and means for automatically extending a calling subscribers' station through a free intermediate conversational link circuit to a free outgoing conversational circuit after a said selector has been set by numerical impulses from a said numerical impulse transmitter.

9. In a telephone system, subscribers' stations, numerical impulse transmitters associated with the said stations, outgoing conversational circuits, intermediate conversational link circuits between the subscribers' stations and the said outgoing conversational circuits, selectors with circuit selecting contacts that always move in the same plane and are affected only in response to said impulse transmitters, means for automatically extending a calling subscribers' station through a free intermediate conversational link circuit to a free outgoing conversational circuit after a said selector has been set by numerical impulses from a said numerical impulse transmitter, and means for disengaging a selector after a calling subscriber's station has been extended.

10. In a telephone system, subscribers' stations, numerical impulse transmitters associated with the said stations, outgoing conversational circuits, intermediate conversational link circuits between the subscribers' stations and the said outgoing conversational circuits, by-paths associated with, and fewer than, the intermediate conversational link circuits, means for connecting any free by-path to a calling subscriber's station when a subscriber makes a call, non-hunting selectors with movable contacts that always remain in one and the same plane connected in the said by-paths, and means for automatically extending a calling subscriber's station through a free intermediate conversational link circuit to a free out-

- going conversational circuit after a said selector has been set by numerical impulses from a said numerical impulse transmitter.
11. In a telephone system, subscribers' stations, numerical impulse transmitters associated with the said stations, outgoing conversational circuits, intermediate conversational link circuits between the subscribers' stations and the said outgoing conversational circuits, by-paths associated with, and fewer than, the intermediate conversational link circuits, means for connecting any free by-path to a calling subscriber's station when a subscriber makes a call, non-hunting selectors with movable contacts that always remain in one and the same plane connected in the said by-paths, means for automatically extending a calling subscriber's station through a free intermediate conversational link circuit to a free outgoing conversational circuit after a said selector has been set by numerical impulses from a said numerical impulse transmitter, and means for disengaging a selector after a calling subscriber's station has been extended.
12. In a telephone system, subscribers' stations, numerical impulse transmitters associated with the said stations, outgoing conversational circuits, intermediate conversational link circuits between the subscribers' stations and the said outgoing conversational circuits, non-hunting selectors with movable contacts that always remain in one and the same plane and adapted to be set by the impulse transmitters, and means for automatically extending a calling subscriber's station through a free intermediate conversational link circuit to a free outgoing conversational circuit after a said selector has been set by numerical impulses from a said numerical impulse transmitter.
13. In a telephone system, subscribers' stations, numerical impulse transmitters associated with the said stations, outgoing conversational circuits, intermediate conversational link circuits between the subscribers' stations and the said outgoing conversational circuits, non-hunting selectors with movable contacts that always remain in one and the same plane and adapted to be set by the impulse transmitters, means for automatically extending a calling subscriber's station through a free intermediate conversational link circuit to a free outgoing conversational circuit after a said selector has been set by numerical impulses from a said numerical impulse transmitter, and means for disengaging a selector after a calling subscriber's station has been extended.
14. In a telephone system, calling lines, wanted lines, a plurality of sets of conversational trunks, a plurality of numerical selecting devices with movable contacts that always remain in one and the same plane, numerical impulse transmitters associated

with the calling lines, conductors for conducting a series of numerical impulses from a calling line into a first said numerical selecting device, means for subsequently conducting a second series of numerical impulses through a plurality of conversational trunks into a second numerical selecting device, and means for subsequently interconnecting a calling and called line through a number of the said conversational trunks in tandem.

15. In combination with a telephone system, an automatic switch with series of bank contacts and a plurality of sets of wipers adapted to move from one series of bank contacts to the next without passing a number of individual contacts of a series, a testing means for testing a whole series of bank contacts at a time, and means for testing each bank contact of a series separately.

16. In combination with a telephone system, a group of automatic switches each provided with series of bank contacts and a plurality of sets of wipers adapted to move from one series of bank contacts to the next without passing a number of individual contacts of a series, a testing means for testing a whole series of bank contacts at a time, means for testing each bank contact of a series separately, means for operating a plurality of these said switches simultaneously, and means for preventing mutual interference of simultaneously operating switches when connections are extended through them.

17. In combination with a telephone system, an automatic switch with series of bank contacts sets and a plurality of sets of wipers adapted to move from one series of bank contacts to the next series, a testing means for testing a whole series of bank contacts at a time, and means for testing each bank contact of a series separately.

18. In combination with a telephone system, an automatic switch with series of bank contact sets and a plurality of sets of wipers adapted to move from one series of bank contact sets to the next without passing a number of individual contacts of a series, a testing means for testing a whole series of bank contacts at a time, and means for testing each bank contact of a series separately.

19. In combination with a telephone system, a rotary automatic switch comprising a plurality of series of bank contacts arranged in different planes, a plurality of sets of wipers adapted to move from one series of bank contacts to the next without passing a number of individual contacts of a series, a driving device for driving the said wipers from one series of bank contacts to another in succession, a testing means for testing a whole series of bank contacts at a time, and a testing means for

testing each bank contact of a series separately.

20. In combination with a telephone system, a rotary automatic switch comprising a plurality of series of bank contacts arranged in different planes, a plurality of sets of wipers adapted to move from one series of bank contacts to the next without passing a number of individual contacts of a series, a driving device for driving the said wipers from one series of bank contacts to another in succession, a testing relay for testing a whole series of bank contacts at a time, and testing relays for testing each bank contact of a series separately.

21. In an automatic telephone system, automatic line finder switches with fixed bank contacts and movable contacts cooperating with the bank contacts, a plurality of trunks of a certain character each connected to the movable contacts of a different finder switch, a plurality of trunks of a different character each connected to the movable contacts of others of the said finder switches, and calling lines connected to the multiples of all of the contact banks of the said finder switches.

22. In an automatic telephone system, automatic line finder switches with fixed bank contacts and movable contacts cooperating with the bank contacts, a plurality of trunks of a certain character each connected to the movable contacts of a different finder switch, a plurality of trunks of a different character each connected to the movable contacts of others of the said finder switches, calling lines connected to the multiples of all of the contact banks of the said finder switches, telephone instruments associated with the calling lines, and means

by which a calling line is always connected to a trunk of a certain character when the telephone receiver is raised from the instrument belonging to the calling line.

23. In an electromechanically controlled telephone system, the combination of a group of trunks, a group of subscriber's lines, a plurality greater than two of sets of intermediate lines for effecting connections between the subscriber's lines and the trunks non-numerical switches, numerical switches with movable contacts that always remain in the same plane and means including a said non-numerical switch for establishing the said connections through lines of all the sets in series.

24. In an electromechanically controlled telephone system, the combination of a group of trunks, a group of subscriber's lines, a plurality greater than two of sets of intermediate lines for effecting connections between the subscriber's lines and the trunks, non-numerical switches, numerical switches with movable contacts that always remain in the same plane; means including a said non-numerical switch and a numerical switch for establishing the said connections through lines of all the sets in series, and means for preventing any line of two of the said sets of intermediate lines from being taken into engagement unless it can form part of a completed connection.

In testimony whereof I have signed my name to this specification in the presence of two subscribing witnesses.

FRITZ ALDENDORFF.
